TYPE SETTING MACHINE

Blackwell K. Murchison, deceased, late of Brooklyn, N. Y., by Bessie F. Murchison, executrix, Brooklyn, N. Y.

Application January 17, 1955, Serial No. 482,041

38 Claims. (Cl. 276—2)

This invention relates to new and useful improvements in type setting machines.

This application is a continuation in part of co-pending patent application Serial Number 212,054, filed February 21, 1951, now U. S. Patent No. 2,749,132.

The invention covers a type setting machine which is capable of setting and justifying an entire line of type at a time. Although the machine deals with each character, symbol or space individually, it justifies an entire series of characters, symbols and spaces forming a complete line of type. As each line of type is set and justified, it may be proof-read and then reproduced by any conventional reproducing process, such as printing, photography, casting, matrix making, stencil cutting and the like. The lines of type may be reproduced by any known printing process, such as contact printing, photo-engraving, photo-offset printing and the like. It is contemplated that the lines of type be printed on both opaque and light transmitting paper for further reproduction through any of the known processes such as photo-printing, blueprinting, the Van Dyke process, the Ozalid process and other well known reproduction processes.

This machine is fully automatic in the sense that once the type is selected, the machine will automatically pick the selected type out of the type magazines, it will automatically set the type and justify it and then, following the reproduction process, it will automatically return the type to their original places in the type magazines. This automatic procedure continues indefinitely, forming one line of type after another, justifying each line of type, reproducing it and then redistributing the type for further use.

To render the machine fully automatic, as above described, two control units are provided. The first control unit directs and controls the selection of the type. This involves selection of the type face, selection of the individual pieces of type within the selected type face group, and selection of type spacers or wedges. The second control unit automatically restarts the type setting machine upon the completion of the reproduction of each line of type. The type selecting control unit utilizes a continuous perforated tape to direct and control the machine in the selection of the type face, the individual pieces of type and the type spacers or wedges. It will however be clearly understood that although a perforated tape operated control unit is herein preferred, other means, such as magnetic tape, may be utilized in connection with the type selecting control unit.

An important feature of this invention is the nature and construction of the magazines for the type and type spacers or wedges. These magazines are a series of coaxial rings of like diameter. These rings are radially slotted to receive and accommodate the type and type spacers or wedges. The slots are so arranged in the rings and the type and type spacers or wedges are so positioned in the slots that the greatest number of individual pieces of type and type spacers or wedges are accommodated in the rings.

2

In the above identified co-pending patent application these rings are shown to be mounted on internal bearings which, in turn, are mounted on an inner drum. It has been found that this inner drum prevents ready access to the individual rings and there are other functional and structural disadvantages which are inherent in the use of an inner drum. In the present invention, the inner drum is eliminated altogether and the rings are mounted on external bearings or rollers which themselves are carried by an open framework. Consequently, the rings are accessible both on the outside and the inside and there are other advantages which make for a structurally and functionally superior machine.

The type spacers or wedges are of novel construction and they perform two important functions. In the first place, they serve as spacers for the purpose of spacing one word from another. In the second place, they cooperate with complementary U-shaped wedges in order to justify a complete line of type. Since justification includes spacing, these spacers or wedges will herein-after be referred to solely as wedges or as type wedges.

An important aspect of this invention is the means by which the type and type wedges are carried from the rings in which they are stored to their operative positions in which they are justified for reproduction purposes. The rings are individually actuated and controlled by the type selecting control unit. The rings are individually caused to engage in angular movement and they are individually stopped in pre-selected angular positions. The selected type and type wedges are now situated directly opposite and adjacent two mechanisms. The first operates to remove the selected type and type wedges from the rings and the second operates to receive said selected type and type wedges.

It is at this point that selected U-shaped wedges are brought into engagement with the selected type wedges. The mechanism for selecting the U-shaped wedges is wholly novel and extremely important to the functioning of the present machine.

The use of these U-shaped wedges in cooperation with the type wedges to justify the type and type wedges and also to lock them in justified and operative positions, requires the use of means for transferring the U-shaped wedges from inoperative to operative positions and also means for moving them relative to the type wedges for justification and locking purposes. The transfer means includes a carrier bar which is also the means of moving the type and type wedges from inoperative to operative positions. Both the type and type wedges on the one hand and the U-shaped wedges on the other hand engage the carrier bar and a mechanism is provided for moving said carrier bar from inoperative to operative position and back to inoperative position.

Laterally moving means is provided to cause the type and type wedges to move toward each other concurrently with their forward movement to operative positions. The same means will move the type and type wedges away from each other on their return movement to inoperative positions. Simultaneously, track means are provided for guiding the U-shaped wedges in synchronization with the lateral movement of the type and type wedges. The tracks are divided into three sections. The back section is vertically movable and it is related to the means which receives the type and type wedges from the type rings and to the means which returns the type and type wedges to said type rings. The back track section is in inoperative position when the type and type wedges are in process of being transferred from or to the type rings. The back track section is in operative position only when the type and type wedges and the U-shaped wedges are in process of being moved toward or away from their operative positions.

The intermediate track section always remains stationary and in operative position. The front track section, like the back track section, is vertically movable into and out of position. It occupies its operative position only when the type and type wedges and also the U-shaped wedges are in movement either toward or away from their respective operative positions. The front track section is moved out of operative position only for the purpose of moving the U-shaped wedges vertically relative to the type and type wedges. When the type and type wedges are in operative positions, the U-shaped wedges are moved upwardly into wedging and locking engagement with the type wedges. The reproduction process may now take place. At the conclusion of the reproduction process, the U-shaped wedges are moved downwardly out of wedging and locking engagement with the type wedges and then the U-shaped wedges re-assume their traveling positions relative to the type and type wedges and the carrier bar. The front track section now resumes its operative position on a level with the intermediate and back track sections, and the carrier bar may now transfer the type and type wedges and the U-shaped wedges back to their positions adjacent the type rings. The type and type wedges are returned to the type rings and the U-shaped wedges are returned to the magazine which stores them.

A preferred form of this invention is shown in the accompanying drawings in which:

Fig. 1 is a plan view of a type setting machine constructed in accordance with this invention, but illustrated without the control units.

Fig. 58 is an enlarged fragmentary section on the line 58—58 of Fig. 55.

Fig. 59 is a view related to Fig. 55.

Fig. 60 is a fragmentary view looking in the direction of arrows 60, 60 of Fig. 59.

Fig. 61 is a view similar to that of Fig. 59 but showing the mechanism in a different position.

Fig. 62 is a view similar to that of Fig. 60 but taken on the line 62—62 of Fig. 61.

Fig. 63 is an enlarged fragmentary view looking down upon the right side of what is shown in Fig. 1, but with the type in justified positions.

Fig. 64 is an enlarged fragmentary view of the switch mechanism indicated by the numeral 64 in Fig. 3.

Fig. 65 is an enlarged fragmentary view of the switch mechanism indicated by the numeral 65 in Fig. 6.

Fig. 66 is a schematic diagram showing the sequence and relative timing of the several operations of the type setting machine constituting the present invention.

Fig. 67 is a schematic wiring diagram which should be appended to the lower end of Fig. 68, Fig. 68 to be appended to the right side of Fig. 69, and all three figures to be read together and comprising the wiring diagram of the entire machine herein claimed.

Fig. 68 is a wiring diagram which should be appended to the upper end of Fig. 67 and to the right side of Fig. 69 and is to be read in conjunction with Figs. 67 and 69 as above indicated.

Fig. 69 is a wiring diagram which should be appended to the left side of Fig. 68, Fig. 68 to be appended to the upper end of Fig. 67 and all three figures to be read together as above indicated.

Fig. 70 is a perspective view of some of the parts of the machine, particularly the type justifying mechanism.

The type setting machine which is herein described and claimed is mounted on a base 100 and it includes a main frame 102 mounted centrally on the base and a secondary frame 104 mounted at the forward end of the base. See Figs. 1, 2 and 5. At the back end of the base is a third frame 106. Main frame 102 carries the type and type wedge magazines, forward frame 104 relates to the type setting and justifying mechanisms and frame 106 supports the locking mechanisms which lock the magazines in appropriate angular positions for accurate selection of the type and type wedges. A fourth frame 108 is provided on the back of the base behind the main frame 102 and it will be seen that this fourth frame supports the drive means by which the type and type wedge magazines are caused to engage in rotary movement. See Figs. 2 and 5.

It has above been stated that the type and type wedges are stored in ring-shaped magazines. These magazines will hereinafter be designated as type rings 110 and it will be seen in the drawing that there is a plurality of such type rings and that they are all of like size and rotatably mounted adjacent each other on a common axis which extends transversely across the machine. Each type support ring is mounted on a plurality of ball bearings 112 carried by blocks 114 which are secured to the crossbars 116 of the main frame 102. It will be noted in Fig. 5 that these crossbars 116 and these blocks 114 are situated on the outside of the type rings, several of these bars and blocks being situated below said rings, and some to the front, back and top of said rings. Fig. 21 shows that it is the outer peripheral edge of the rings which rides upon and is supported by bearings 112.

Adjacent the end ring on each side of the machine is a stationary ring 118 which is secured to the main frame 102. Crossbars 116 are secured to said stationary rings

and the type rings are consequently retained between the two end rings 118 and also within the cage which the crossbars 116 define. See Fig. 25. Referring to Fig. 25 and also to Fig. 26, it will be seen that crossbars 116 are secured by means of bolts 120 to the outer circumferential edge of stationary rings 118 and that other crossbars 122 are secured by means of bolts 124 to the inner peripheral edge of said stationary rings.

Tubular members 126 are inserted into holes formed for said tubular members in crossbars 122. It will be noted that plungers 128 are slidably mounted in said tubular members and compression springs 130 are provided in said tubular members to engage said plungers and to urge them toward and into engagement with the type rings. A cap 132 on said tubular members holds the springs in place and it will be understood that this cap may be removably secured to said tubular members by any conventional means, such as screw threads and it will further be understood that the tubular members themselves may be secured to the crossbars 122 by any conventional means. Bushings may be provided for said tubular members, if desired. See Fig. 26. It will herein-after be seen that plungers 128 serve as contact brushes in the electrical system which controls the present machine.

It has been stated that plungers or brushes 128 are spring urged into engagement with the type rings. More specifically, each type ring has a pair of inner insulating rings 134 and 136 secured thereto by means of screws 138 and contact ring segments 140 and 142 are secured by screws 144 to said inner rings. Plungers or brushes 128 bear against contact ring segments 140 and 142 as Figs. 25, 26 and 27 clearly show.

Referring again to Figs. 25, 26 and 27, it will be noted that stop bars 146 are mounted on cross-bars 122 between the inner contact ring segments 140 and 142. These stop bars are mounted on blocks 148 and they are secured to crossbars 122 by means of bearings 150. It will be noted that these stop bars are tapered at both ends. It will be understood that the contact ring segments 140 and 142 are not full rings. Consequently, contact between said contact ring segments and the plungers or brushes 128 is interrupted periodically and said plungers or brushes would normally tend to move radially outwardly under the influence of the compression springs which engage them. To prevent such outward movement and consequent dislodgment of said plungers or brushes, these stop bars 146 are provided to support the plungers or brushes when they are disengaged from the contact ring segments.

Another important structural feature of the mechanism under discussion is the use of bearings 150 between adjacent type rings. See Figs. 21, 22 and 25. These bearings are recessed into one of the sides of each type ring so that the bearings of one ring will bear against the adjacent ring. Each bearing 150 is mounted on a pin 152 which extends radially of the central axis of the type rings. A plate 154 secures pins 152 to the type rings and there is an opening in said plate through which the bearings 150 project into engagement with the adjoining rings. It is by this means that the several type rings are enabled to rotate relative to and freely of each other while remaining situated in close proximity to each other.

Secured to each type ring, on one side thereof, is a gear ring 156. Engaging each such gear ring is a gear wheel 158. Each gear wheel 158 is secured to a shaft 160 to which a worm wheel 162 is secured. A worm 164 engages each worm wheel 162. The worm is supported by bearings 166 and 168 in a block 170. Block 170 is hollow and it may be described as a gear box not only for the worm but also for the worm wheel and it also supports gear wheel 158 although said gear wheel is mounted externally of said gear box rather than internally thereof as is the case with the worm and the worm wheel. It will be noted that bolts 172 secure the

gear box to the crossbars 116 to hold the gear wheel 158 in mesh with gear ring 156. See Figs. 21, 22 and 23. It will be noted, particularly in Figs. 22 and 23, that a bearing 174 may be employed to rotatably support each gear wheel 158 and worm wheel 162.

Secured to each worm 164 is a flexible drive shaft 176 and it will be seen in Figs. 2 and 5 that each flexible drive shaft is secured to the shaft of an electric motor 178. There are as many motors 178 and flexible drive shafts 176 as there are type rings. The motors are staggered relative to each other both in side and end view. See Figs. 2 and 4. It is in this way that the motors may all be grouped in the smallest possible space and in closest proximity to the type rings. Frame 108 is shown to include a plurality of stepped shelves 180 to support the motors in accordance with the arrangement above indicated. It will be understood from the foregoing that when the motors are energized, they will cause the several type rings to which they are individually connected by means of drive shafts 176 and the worms and worm wheels 164 and 162 and gear wheels 158 and gear rings 156, to engage in angular or rotary movement.

Although the type rings may all turn simultaneously, they will not all travel the same angular distances and they will not all stop at the same time. It is this angular movement of the type rings which brings the selected pieces of type and type wedges to the transfer station whence they are transferred to operative positions. A complete line of type will require the delivery of a plurality of type and type wedges and while the pieces of type may not all be different, the great majority of them will be. It will hereinafter be seen that the pieces of type are all stored in corresponding places in the several type rings and consequently the type rings would necessarily be required to assume different angular positions in order to bring the selected pieces of type and type wedges to the transfer station.

It has been stated that motors 178 provide the motive power for causing the type rings to engage in angular movement. Solenoids 182 provide the motive power for stopping the type rings in preselected angular positions. It will be seen in Figs. 2 and 4 that these solenoids are supported by brackets 184 which are mounted on a vertical board 186 that is secured to frame 106. Secured to the plunger 188 of each solenoid is a link 190 and pivotally secured at one end to said link is a bell-crank 192 whose fulcrum is pin 194 secured to a bracket 196. Bracket 196 is secured to board 186 and it will be seen that that portion of the bell-crank which is situated between pin 194 and link 190 projects through an opening 198 formed in board 186. See Fig. 19.

Still referring to Fig. 19, it will be noted that the opposite end of each bell-crank 192 is pivotally secured by means of pin 200 to a thrust rod 202. The opposite end of thrust rod 202 is reduced to form a tongue 204 which engages in a slot 206 formed at one end of a second thrust rod 208. See Fig. 20. The two rods 202 and 208 are pinned to each other by means of a cross-pin 210. Pin 210 may be fixed to rod 208 but it projects through an elongated slot 212 formed in tongue 204. The two rods are therefore free to move slightly relative to each other longitudinally of themselves and it will be noted that they extend along a substantially common longitudinal axis.

Again referring to Figs. 19 and 20, it will be noted that a collar 214 is secured to thrust rod 202 intermediate its ends. A second collar 216 is slidably mounted on thrust rod 202 immediately adjacent the second thrust rod 208. A compression spring 218 is mounted on the first thrust rod 202 between its two collars 214 and 216 and the action of this spring is to push collar 216 as far over to the right as it will go, as viewed in Figs. 19 and 20. It will be seen in Fig. 20 that the diameter of thrust rod 208 exceeds the diameter of thrust rod 202.

Consequently, collar 216 will be held in abutment with rod 208 by reason of the action of spring 218.

Secured to the free end of thrust rod 208 is a brake 220 which is simply a toothed plate constituting a rack gear. Thrust rod 208 is slidably mounted in bearing 222 which is secured to a cross-bar 224 whose ends are supported on side bars 226. These side bars are fastened to and supported by the main frame 182 and the back frame 106 and the crossbar 224 is thereby firmly held in fixed position adjacent the type rings. By the same token, bearings 222 are firmly held in position adjacent said type rings and it will be understood that there is one such bearing and one rack gear 220 for each type ring.

15 The action of the type ring braking or locking mechanism last above described is as follows: It is assumed that the type rings are engaged in angular movement. When each type ring reaches a pre-selected angular position, the solenoid 182 which is individual to it will be energized and its plunger will be retracted. Bell-crank 192 will thereby be caused to turn in clockwise direction as viewed in Fig. 19 and thrust rod 202 will be thrust rightwardly as viewed in said Fig. 19, substantially longitudinally of itself. Collar 216 will thereby thrust rod 208 rightwardly until the rack gear 220 engages the teeth of gear ring 156. This, of course, will instantaneously lock the type ring against further angular movement. Spring 218 will yield in the event that the teeth of the rack gear engage the teeth of the gear ring rather than the valleys between the teeth of the gear ring. To that extent there will be lost motion under tension between the two thrust rods 202 and 208 but as soon as the teeth of the rack gear clear the teeth of the gear ring, spring 218 will thrust rod 208 forwardly until its teeth mesh with the teeth of the gear ring to lock the gear ring against further movement.

Reference has been made to the type rings as constituting the type and type wedge magazines. Referring now to Figs. 42 and 43 it will be seen that each type ring 110 has a plurality of radial slots 228 formed therein in close proximity to each other. These radial slots are open at both ends and it is in said slots that the type and type wedges are stored ready for use. Each type ring has only a single series of slots 228 in the sense that all of the slots occupy a common plane to which the central axis of the several type rings is perpendicular. The slots may occupy the full 360° circumference of each type ring and they should be equidistantly spaced from each other.

50 Figs. 38 and 39 are perspective views of a typical piece of type 230 and a typical type wedge 232, respectively. It will be noted in Fig. 41 that slots 228 of the type rings 110 are rectangular in end view. They are not, however, square and it will be observed that in end view the pieces of type are also rectangular but not square. When the type pieces are so oriented that the type may be read right-side up, it will be observed that the type pieces are taller or longer in their vertical dimensions than they are wide. The type slots, however, are so arranged, that the pieces of type will enter only if they are turned upon their sides. See Fig. 41. It is in this way that the greatest number of slots may be formed in the circumference of a type ring of given dimensions and, by the same token, it is in this manner that the greatest number of type pieces and type wedges may be stored in a type ring of given dimensions.

55 Type slots 228 are open at both ends for an important reason. They are open at their outer ends since it is through said ends that the type and type wedges are inserted into and removed from said slots. They are open at their inner ends since it is through said inner ends that the prongs or arms 234 of push-out comb 236 are enabled to enter said slots in order to push the type and type wedges out of the slots. See Fig. 42.

60 Referring now to Figs. 2, 10 and 28, it will be seen that a pair of bars 238 are secured by means of bolts

240 to horizontal side frame members 242 of the main frame 102. A crossbar 244 is secured by means of screws 246 to the forward ends of bars 238. It will be noted that crossbar 244 is situated within the type rings and adjacent their inner peripheral edges. More specifically, crossbar 244 is located immediately behind the push-out station where the type and type wedges are pushed out of the type rings and, of course, this is the same station at which the type and type wedges are pushed back into the type rings. Crossbar 244 has a plurality of transverse holes 248 formed therein which register with prongs or arms 234 of the push-out comb and which receive and guide said prongs or arms so that they will enter the precise type slots which are situated at the push-out or transfer station. This, of course, is predicated upon longitudinal movement of said prongs or arms rightwardly as viewed in Figs. 2 and 28.

The mechanism that causes the comb to move rightwardly, that is, forwardly, is best shown in Fig. 10. It will be seen that push-out comb 236 is slidably mounted for movement along bars 238 and 242. Bars 238 are provided with upwardly projecting portions or blocks 250 at their back ends and it will also be noted that crossbar 244 projects upwardly as well as laterally from the forward ends of said bars 238. Guide bars 252 are secured at their respective ends to crossbar 244 and blocks 250. Comb 236 rides between bars 238 and 242 on the one hand and bars 252 on the other hand and the comb is free to move either forwardly or backwardly as the case may be. Bearings may be provided to prevent lateral movement of the comb in either direction, that is, longitudinally of itself and sidewardly of the machine as a whole.

A headed pin or screw 254 is secured to each end of the push-out comb 236 as Fig. 28 clearly shows. This pin or bolt projects through a slot 256 formed in the upper end of a bar 258. There are, of course, two such bars 258 and they are pivotally secured at their lower ends to the main frame 102 by means of bolts 260. A rod 262 is pivotally secured at its back end by means of pin 264 to each of the two bars 258 and the forward end of each rod 262 is pivotally secured to the upper end of another bar 266 which, in turn, is pivotally secured by means of a bolt 268 to a bracket 270 on frame 104. See Fig. 10.

Still referring to Fig. 10, it will be noted that bars 258 and 266 occupy substantially parallel vertical positions. Rods 262 occupy horizontal positions. It will be observed that pivotal movement of bars 266 about bolts 268 in either direction, that is, either forwardly or backwardly, will produce a corresponding movement of bars 258 and this, of course, will cause the push-out comb to move in the same direction. The means whereby such movement of bars 266 is effected comprises a cam follower 272 on each of the two bars 266, a cam 274 which cooperates with each said cam follower, and a shaft 276 to which said cam is affixed.

Cam 274 engages in rotary movement in the direction of arrow 278 shown in Fig. 10. Since cam 274 is fixed to shaft 276, this is also the direction of travel of said shaft. Shaft 276 is journaled into suitable bearings on side frame members 280 which are secured by means of bolts 282 to the front frame 104. Shaft 276 is the main cam shaft of the entire machine and it operates all of the important mechanical movements thereof. This shaft does not, however, carry the cams of the electrical system of the machine as will hereinafter more fully appear. An electric motor 284 is mounted on base 100 as Fig. 3 clearly shows and it drives a speed reducing gear train in gear box 286. See Fig. 50 and also Fig. 5. It will be seen that a gear wheel 288 connected to the shaft 290 of gear box 286 engages a gear wheel 292 which is fixed to shaft 276. It is by this means that said shaft is caused to rotate at a predetermined number of revolutions per minute.

Referring once again to Fig. 10, it will be seen that cam follower 272 rides within a cam track 294 formed in cam 274. This cam track has four main sections. The largest of these sections is identified in the drawing as 294a and it is situated the greatest distance from the axial center of shaft 276. When the cam follower 272 rides in cam track section 294a, bar 266 is maintained in its leftward position as shown in Fig. 10 and the push-out comb is thereby maintained in inoperative position, that is, free of engagement with the type and type wedges. The second cam track section which the cam follower engages is the inwardly projecting section 294b. This section pulls the cam follower rightwardly and consequently bar 266 and bar 258 and the push-out comb will also be moved rightwardly. This brings the prongs or arms of the push-out comb into engagement with the type and type wedges and pushes them out of their respective slots in the type rings.

The third section is 294c and it will be noted that it 20 swings away from the axial center of shaft 276 but not quite as far from said axial center as the first section 294a is situated. The effect of the engagement of cam follower 272 with the third cam track section 294c is to thrust the push-out comb slightly leftwardly as viewed 25 in Fig. 10, that is, backwardly, to release the type and type wedges temporarily. The fourth cam track section 294d is similar to the second section 294b and the push-out comb is once again caused to move rightwardly (forwardly) into engagement with the type and type wedges. When the cam follower once again engages the first cam track section 294a, the push-out comb is thrust leftwardly (backwardly) to its original inoperative position as shown in Fig. 10.

The extent or range of the movement of the push-out 35 comb between its two extreme positions above mentioned will, of course, be determined by the radial distances between the several cam track sections of cam 274 and the axial center of shaft 276 and also by several other considerations such as the distance between cam follower 272 and rod 262 and between rod 262 and the push-out comb. There is a further element which is provided to determine the precise positions of the push-out prongs or arms relative to the type and type wedges and relative to the type rings when the push-out comb is in its several 40 positions above set forth. This element or feature is 45 provided to determine the precise positions of the push-out prongs or arms relative to the type and type wedges and relative to the type rings when the push-out comb is in its several positions above set forth. This element or feature is best shown in Figs. 43, 44 and 47 where it will be seen that a set screw 296 is set into the push-out comb 236 for engagement with each of the push-out arms 234. More particularly, there is one such set screw for each 50 push-out arm. These set screws engage the back ends of the push-out arms and lock them in place in the horizontal holes 298 which are formed for them in the backbone of the push-out comb. Each push-out arm is individually adjustable longitudinally of itself so that it may 55 be set in precisely proper relation to the type ring to which it relates.

It will be seen in Fig. 43 that when the push-out comb 236 moves rightwardly (forwardly) the type and type wedges which have been selected for a particular 60 line of type are pushed out of the type ring slots in which they were housed and they are pushed into and partly through openings 300 formed in cylinders 302. The selected pieces of type and type wedges are brought to a stop against the ends of horizontal stop rods 304. See 65 Figs. 42 and 43. Stop rods 304 are supported at their forward ends by a crossbar 306 into which they are set. Their back ends are supported by crossbar 309 and it will be noted that it is their back ends which the type and type wedges engage when they are pushed out of the type rings.

Cylinders 302 last mentioned perform a very important function. It has been stated that the type and type wedges are stored on their sides in the slots of the type rings. It is necessary to turn them ninety degrees to their upright positions before they can be used. Cylinders

302 perform the function of first turning the type and type wedges to their upright positions so they may be used and then turning them back upon their sides so that they may be returned to the slots in the type rings.

It will be seen in Fig. 34 that each cylinder 302 is rotatably mounted for angular movement about its own longitudinal axis in a hole 305 formed in bar 306. Bar 306 is secured at its ends to the top of front frame 104 and it is held rigidly in place. It will be noted that an annular flange 308 on one end of each cylinder 302 engages one side of bar 306. A plate 310 which is secured to the opposite end of cylinder 302 by means of screws 312 engages the opposite side of bar 306 and the cylinders are thereby locked in place in their respective holes 305 but, as has above been stated, they are free to turn on their longitudinal axes. See Fig. 34.

It will be seen in Figs. 45 and 46 that opening 300 in cylinder 302 is rectangular in shape and is large enough to accommodate either a piece of type 230 or a type wedge 232. A channel-shaped member 314 is fixed in rectangular opening 300 and it is in said channel that the type or type wedge is lodged after it leaves or before it re-enters the type ring. Consequently, channel 314 will hereinafter be referred to as the type channel of cylinder 302. Also fitted within opening 300 and between the arms of type channel 314 is a leaf spring 316 which bows inwardly toward the yoke of channel 314. The back end of the leaf spring is secured to the back end of type channel 314 by means of a collar 318. See Fig. 34.

When the push-out comb 236 pushes the type and type wedges into type channels 314, leaf spring 316 will engage them and push them rightwardly as viewed in Fig. 45. This is the first step in the process of centering the type and type wedges in the aligning cylinders 302. It will be noted in Figs. 32 and 34 that there is a radial opening 320 in each cylinder 302 and a corresponding opening in type channel 314 which registers with opening 320 to provide communication with the inside of said cylinder and said channel.

Projecting into the type aligning cylinder 302, through radial opening 320, is a bar 322 which is secured by means of one or more screws 324 to crossbar 306. See Fig. 33. It will be noted that bar 322 occupies a vertical position and that it is set into the front face of crossbar 306 in order for it to clear the annular flange 308 of cylinder 302. It will be noted in Fig. 45 that the inwardly projecting end of bar 322 engages the lower edge of type 232 when the type is in substantially vertical position. But when the type is so situated in cylinder 302 that it lies flat on its side, there is no engagement between the type and bar 322. See Fig. 43. It will be recalled that when the type and type wedges are pushed into the type aligning cylinders 302, they lie flat on their sides. It will now be understood that in this condition leaf spring 316 acts upon one side of the type or type wedge and holds it flat against the yoke of the type channel 314. See Fig. 43.

It is necessary to turn the aligning cylinders 302 a full ninety degrees in order to swing the type and type wedges to their substantially vertical positions as indicated in Figs. 44 and 45. The mechanism for turning the cylinders includes plates 310 which are secured to the type aligning cylinders 302. See Fig. 29. It will there be noted that each plate 310 includes a disc-shaped portion 310a and an elongated arm 310b having an elongated slot 310c formed therein, longitudinally of said arm. The disc-shaped portion 310a is also provided with a rectangular opening 310d through which the type channel 314 and spring 16 may extend and through which the type or type wedges may be inserted into or removed from said aligning cylinders 302.

Projecting through each slot 310c is a pin 326. These pins 326 are secured to a crossbar 328 which is slidably mounted within a channel 330 formed in crossbar 306. 75

The slideable movement of crossbar 328 is longitudinally of itself and of crossbar 306 and transversely of the machine as a whole. This movement of bar 328 is effected by the following means: It will be noted in Figs. 30 and 31 that bar 328 is provided with gear teeth 330 along its bottom edge and that said gear teeth are engaged by a gear wheel 332. This gear wheel is mounted on a stud shaft 334 and is secured thereto by means of a set screw 336. Stud shaft 334 is journaled into fixed crossbar 338 and a second gear wheel 340 is fixed to said stud shaft by means of set screw 342.

Referring now to Figs. 29 and 16 it will be seen that a rack gear 344 is slidably mounted at its upper end in block 346 and that it is in mesh with gear wheel 340. 15 The lower end of rack gear 344 is secured by means of screws 348 to a vertically extending bar 350. At the lower end of bar 350 is a nut or a collar or a pair of nuts or collars 352. Above these nuts or collars is a plate 354 and there is a compression spring 356 on said bar 350 above said plate 354. Another collar 358 is secured to bar 350 and it will be noted that said spring 356 bears upwardly against said collar 358 and downwardly against said plate 354. Plate 354 is secured to a horizontally extending bar 360 which is pivotally secured by means of bolt 362 to frame 104. Bolt 362 is at one end of bar 360 and plate 354 is at its opposite end. Intermediate the ends of bar 360 is a cam follower 364 which rides within cam slot or track 366 of cam 368. This cam, like cam 274 above mentioned, is fixed to cam shaft 276 which rotates in the direction of arrow 370 in Fig. 16.

Cam track 366 has two major sections. The larger of these two sections is identified in the drawing by means of the reference character 366a. The smaller section is identified as 366b. It will be noted that section 366a in which cam follower 364 is shown to be disposed in Fig. 16 is much closer to the axial center of shaft 276 than is cam track section 366b. Consequently, when the cam follower 364 is in section 366a, bar 360 will be pulled downwardly in clockwise direction about bolt 362 as viewed in Fig. 16 and bar 350 and rack gear 344 will be pulled downwardly. This will have the effect of causing gear wheel 340 to turn in counter-clockwise direction as viewed in Fig. 29 and since gear wheel 332 is fixed to a common shaft with gear wheel 340, said gear wheel 332 will be caused to turn in the same direction. Bar 328 will accordingly be caused to move leftwardly as viewed in Fig. 29 to the position which it is shown to occupy in said Fig. 29.

When cam 368 rotates with shaft 276 to bring track section 366b in engagement with cam follower 364, the result will be to move bar 360 upwardly and with it bar 350 and rack gear 344. Gear wheels 340 and 332 will now be caused to turn in clockwise direction as viewed in Fig. 29 and bar 328 will be caused to move rightwardly as viewed in the same figure. Pins 326 on bar 328 will, of course, move with said bar and arms 310b of plates 310 will thereby be caused to swing in counter-clockwise direction about the central axis of cylinders 302 a full ninety degrees, and cylinders 302 will move integrally with said plates.

This movement of bar 328 first in one direction and then in the opposite direction is synchronized with the movements of all of the other parts of the machine above described. Consequently, the cylinders will be turned ninety degrees from their positions in Fig. 29 so as to be able to receive the type and type wedges from the type rings as viewed in Fig. 43. The cylinders will then be turned to their positions in Fig. 29 and Figs. 44, 45 and 46 in order to turn the type and type wedges to their vertical, operative positions.

It is when said cylinders 32 are turned to their last mentioned positions, that the lower edges of the type and type wedges strike the upper ends of bars 322. See Fig. 45. The type and type wedges are thereby brought into a central position in the cylinder openings 300 and

this is done against the action of leaf springs 316 which would normally urge said type and type wedges against the yoke of the type channels 314. It is important at this point to understand that the pieces of type may not all be of the same thickness. Consequently, it may be necessary to provide a recess 230a in the lower right hand corner of the thicker pieces of type, as viewed in Fig. 41, so as to reduce the thickness of said pieces of type at their respective front ends in order to correspond to the thickness of the thinner pieces of type. With these recesses, all pieces of type, irrespective of their thickness, would be positioned centrally in cylinder openings 300 by reason of their engagement with bars 322. It will of course be understood that these bars will engage the recessed ends of the thicker pieces of type.

The type and type wedges are now centered in the aligning cylinders 302 but they do not stand in precisely vertical positions. See Fig. 45. It is now necessary to swing the type and type wedges to perfectly parallel positions and in true vertical alignment. This is accomplished by the apparatus shown in Figs. 31, 32 and 46. Positioned above each type cylinder 302 is a pivotally mounted type aligner 372. This type aligner has a shank 374, an enlarged back end 376, and a bifurcated head 378. A hole 380 is formed in the enlarged back end portion 376, transversely thereof, to receive a shaft 382 which extends transversely of the machine as a whole. The type aligner 372 is free to pivot about the longitudinal axis of shaft 382. It will be noted in Fig. 46 that the bifurcated head 378 has a vertically extending slit 384 formed therein and it is said slit which gives the head its bifurcated character.

The lower ends of the two parts of the bifurcated head 378 are provided with beveled surfaces 386 and 388 respectively and it will be noted in Fig. 46 that these two beveled surfaces converge in upward direction to form the substantial equivalent of an inverted V. It will be apparent that these beveled surfaces will serve as cam faces to cam the type and type wedges into perfectly vertical positions upon engagement of said cam faces therewith. This engagement is effected by reason of the action of compression springs 390 whose lower ends project into a recess 392 formed in the shank 374 of type aligners 372. The upper end of springs 390 projects into a hole 394 formed in cross-bar 396. Screw plugs 398 in said holes 394 abut the upper ends of compression springs 390 and the tension of said springs may be adjusted by adjusting the positions of said screw plugs 398. These compression springs bear downwardly upon the type aligners 372 and urge them to swing downwardly in counter-clockwise direction as viewed in Fig. 32 into engagement with the type and type wedges as shown in Fig. 46 in order to cam said type and type wedges into perfectly vertical positions.

The normal position of type aligners 372 is, however, elevated against the action of the compression springs 390. This is an inoperative position in which the type aligners are out of engagement with the type and type wedges. The means for holding the type aligners 372 in elevated position includes a collar 400 which is secured to shaft 382 by means of set screw 402. An arm 404 projects forwardly from collar 400 and it will be noted that this arm engages the bottom of a pin 406 which is secured to each type aligner 372 and projects laterally therefrom. See Fig. 31. It will hereinafter be seen that means are provided for turning shaft 382 about its own longitudinal axis. When the shaft is turned in clockwise direction as viewed in Fig. 31, arm 404 will push upwardly against pin 406 and the type aligner will thereby be elevated against the action of spring 390. When shaft 382 turns in counter-clockwise direction as viewed in Fig. 31, arm 404 will swing downwardly and type aligner 372 will be enabled to swing downwardly into

engagement with the type and type wedges under the action of spring 390.

The mechanism for turning shaft 382 upon its own longitudinal axis is shown in Figs. 2 and 9. This mechanism includes a crank arm 408 which is fixedly secured at one end to shaft 382 and which is pivotally secured at its opposite end to rod 410 by means of bolt 412. The lower end of rod 410 projects through a plate 414 and is prevented from pulling out of said plate by means of nuts or collars 416. An extension spring 418 is secured at its upper end to frame 104 and it is secured by means of bolt 420 at its lower end to the lower end of rod 410. Spring 418 acts to pull rod 410 upwardly, substantially longitudinally of itself, and this would have the effect of swinging the crank arm and shaft 382 in clockwise direction as viewed in Fig. 9. This would have the further effect of releasing the type aligners 372 for downward movement under the action of springs 390 into engagement with the type and type wedges.

Plate 414 is secured to one end of a bar 422. The opposite end of said bar is pivotally secured by means of bolt 424 to frame 104. Intermediate the ends of bar 422 is a bracket 426 which supports a cam follower 428. This cam follower engages the outer edge of cam 430 which is secured to cam shaft 276. The cam follower 428 is held in engagement with said cam 430 by reason of the pulling action of spring 418 on plate 414 which is secured to bar 422. The outer edge of cam 430 is divided into several cam face sections. The section which the cam follower 428 is shown to engage in Fig. 9 is identified as cam section 430a. This cam section is farthest away from the axial center of shaft 276 and its purpose is to push arm 422 downwardly and thereby to turn shaft 382 in counter-clockwise direction as viewed in Fig. 9 to elevate the type aligners 372 to inoperative position.

The next cam section 430b is situated nearer the axial center of shaft 276 and this cam section functions to allow arm 422 to swing outwardly under the influence of spring 418. This will have the effect of moving rod 410 upwardly and shaft 382 in clockwise direction in order to free the type aligners 372 for downward movement under the influence of springs 390 into engagement with the type and type wedges. The next cam section along the outer peripheral edge of cam 430 is section 430c. This is a small section which is as far removed from the center of shaft 276 as is the much larger cam section 430a and the purpose of section 430c is to disengage the type aligners 372 temporarily from the type and type wedges. The final section 430d is also a short section and it corresponds in its distance from the axial center of shaft 276 to section 430b above mentioned. Its purpose is to enable the type aligners 372 to re-engage the type and type wedges. The process is of course continuous and repetitious through the four stages thus described. In this connection it should be remembered and understood that there is need to position the type and type wedges vertically only upon their removal from the type rings and preparatory to being transferred to operative positions. There is no need to align them in this manner 60 in order to return them to the type rings since they are returned when they are flat on their sides, held flat against the yokes of the type channels 314 by means of leaf springs 316.

Now that the type and type wedges are vertically positioned, reference must be made to recess 432 formed in the bottom of each piece of type 230 and corresponding recess 434 formed in the bottom of each type wedge 232. See Figs. 38 and 39. When the type and type wedges are disposed flat upon their sides as viewed in Fig. 43, 70 they rest upon a crossbar 436 on carrier or transfer bar 438. When the type and type wedges are turned right side up as shown in Fig. 44, their respective recesses 432 and 434 receive and engage crossbar 436 to prevent any longitudinal movement of said type and type wedges 75 relative to the carrier bar 438. Lateral movement of

said type and type wedges longitudinally of crossbar 436 and carrier bar 438 is, however, permitted. See also Fig. 42. It will shortly appear that this carrier bar 438 is the means for transferring the type and type wedges to their operative station and then back on their return to the type rings.

Wedge 232 is, in a sense, a passive element. It requires a second wedge element, an active wedge element, to complement and cooperate with it. Fig. 40 is a perspective view of a U-shaped wedge element 440 which serves as the active wedge element in cooperation with the passive wedge element 232. It will be noted that U-shaped wedge 440 has a yoke 442 and a pair of arms 444 and 446 respectively. These two arms project at right angles from yoke 442 and they are parallel to each other. It will be seen that these two arms taper from relatively thick proportions adjacent the yoke to relatively thin proportions at their free ends. In edge view (see Fig. 48, for example) the U-shaped wedge 440 is provided with arms which are as thick at their base as the yoke from which they project and which taper on only one side to a relatively thin point. The opposite side is straight.

Fig. 40 shows that yoke 442 of the U-shaped wedge is provided with an open notch or slot 448 at one end and with a longitudinally extending pin 450 midway between the ends of said yoke. The pin 450 projects in the opposite direction from yoke 442 from the direction in which the two arms 444 and 446 project. It should also be noted that that edge of the yoke from which pin 450 projects is somewhat arcuately shaped so that the pin projects from the highest point thereon.

Each wedge 232 is provided with a pair of spaced tapered recesses 452 and 454 respectively. These tapered recesses are formed on one side only of each wedge 232 and it will be noted that the spacing of these recesses corresponds to the spacing of arms 444 and 446 of the U-shaped wedge 440. Moreover, the taper of these two recesses corresponds to and complements the taper of said arms.

The wedging action which locks and justifies the type takes place when one U-shaped wedge 440 engages each selected wedge 232 and is moved upwardly relative thereto as far as it is permitted to go. The tapered side of the two arms of the U-shaped wedge will engage the tapered recesses of wedge 232 but since the taper of the arms and the taper of the recesses complement each other, there will be no torsional force exerted upon wedge 232 which will tend to twist it out of its vertical position. The non-tapered side of the two arms of U-shaped wedge 440 and the non-tapered sides of wedge 232 will occupy parallel vertical planes irrespective of how high the arms of said U-shaped wedge are driven up into the tapered recesses of said wedge 232.

U-shaped wedges 440 are supported side by side, but in spaced relation to each other, on a crossbar 456 which has a front wall 458 and a plurality of channel-shaped members 460 along its back edge. These channel-shaped members 460 are each provided with two laterally extending flanges 462 which are fastened by means of screws 464 to the front wall 458. These channel-shaped members 460 are relatively deep and they form pockets for the U-shaped wedges 440. There is one such pocket 460 for each U-shaped wedge 440. It will be noted that the upper ends of the side walls of said pockets 460 flare outwardly to form wings 466 which define a tapered approach to the inside of said pockets. The U-shaped wedges 440 are normally stored in said pockets 460 until they are selected for use. See Figs. 59 and 60.

A selecting mechanism is provided in the machine to select the U-shaped wedges 440 for use in connection with the selected wedges 232. For each wedge 232 which is selected for use in connection with a given line of type there is a U-shaped wedge 440 for engagement therewith. The selecting mechanism makes use of a notch 468 formed

in the bottom of each wedge 232 a spaced distance behind recess 434 and immediately behind tapered recess 452. See Fig. 39. It will be apparent from an examination of Fig. 38 that there is no notch in type 230 corresponding to notch 468 in wedge 232. Referring now to Figs. 55 and 59 it will be seen that a probe bar 470 is engageable with each piece of type 230 and each wedge 232 selected for a given line of type. Reference to Fig. 60 will show that at the upper end of each probe bar 470 is a laterally extending lug 472. It is this lug which is engageable with the type and type wedges as Fig. 60 clearly shows. When these probe bars 470 are brought into engagement with the type and type wedges by the means which will shortly be described, lugs 472 will enter notches 468 and the probe bars will thereby be enabled to distinguish between the type and type wedges. When a notch 468 is encountered, the probe bar will be elevated to a higher level than when such notch is not encountered. Consequently, each probe bar 470 which engages a wedge 232 will rise to a higher level than the probe bars which engage the pieces of type 230. See Figs. 55, 59 and 60.

The lower ends of the probe bars 470 are secured to the lower ends of expansion springs 474. The upper ends of said springs are secured to an angle bar 476 which is fixed to frame 104. These expansion springs 474 act to urge the probe bars upwardly into engagement with the type and type wedges. The probe bars may be supported for vertical slidable movement in any suitable manner, for example, in slots 478 formed in bar 456 and corresponding slots 480 formed in angle bar 476, slots 480 and slots 478 being in registration with each other. A bar 482 is secured by means of screws 484 to the slotted edge of bar 456 and another bar 486 may be secured to the slotted edge of angle bar 476 in order to lock the probe bars in their respective places in slots 478 and 480 while allowing them to slide vertically in either direction therein.

Each probe bar 470 is provided with a laterally extending lug 488 which is engageable with a stop plate 490. Normally stop plate 490 is disposed at a relatively low level. Springs 474 urge the probe bars 470 upwardly but they are prevented from engaging the type and type wedges by reason of the engagement of lugs 488 with stop plate 490. It is only when the stop plate moves upwardly that engagement between the probe bars and the type and type wedges is possible. Compare Figs. 59 and 60 on the one hand with Figs. 61 and 62 on the other hand.

The mechanism for raising and lowering the stop plate 490 is shown in Figs. 11 and 55. It will be seen that stop plate 490 is provided with a downwardly extending web portion 492 along its front edge and a forwardly extending horizontal portion 494 connected to the lower edge of said web portion. Horizontal portion 494 is secured to an angle bar 496. Angle bar 496 is secured at both ends to arms 498 which are pivotally mounted by means of pins 500 on brackets 502. These brackets 502 are secured by means of screws 504 to vertical bars 506 which, in turn, are secured by means of screws 508 to crossbar 510, said crossbar being fixedly secured at its ends to frame 104. Since plate 490 and lugs 488 are in engagement with each other and said lugs are urged upwardly by reason of the fact that they are secured to probe bars 470 which themselves are urged upwardly by spring 474, plate 490 and angle bar 496 and arms 498 will be urged to swing upwardly in counter-clockwise direction about the pivotal axis of pins 500 as viewed in Fig. 11. In Fig. 59, such movement would be in clockwise direction.

A second arm is pivotally connected to each or to either of the two brackets 502. This arm 512 is pivotally secured to each or either bracket 502 by means of pin 514. An adjusting screw or stop screw 516 is secured to a horizontal end piece 518 at one end of bar 512 and it will be seen that this screw engages the top of one of the pivoted arms 498. At the opposite end of arm 512 is a bracket 520 which supports a cam follower 522. This

cam follower rides on a cam 524 which is mounted on shaft 276. The direction of rotation of said shaft and said cam is indicated by the curved arrow 526 in Fig. 11.

Cam 524 has two sections. The larger cam section 528 is situated at a greater distance from the axial center of shaft 276 than the smaller cam section 530. Fig. 11 shews the cam follower 522 to be in engagement with the larger cam section 528 and in such case arm 512 is rocked slightly in a clockwise direction so as to enable the adjusting or stop screw 516 to swing arm 498 downwardly in clockwise direction. This, of course, causes the probe arms 470 to move downwardly against the action of springs 474. When the cam follower 522 is brought into engagement with the smaller cam section 530, arms 498 and 512 will swing in counterclockwise direction under the influence of springs 474 and the probe bars 470 will rise.

The probe bars 470 will now engage the type and type wedges 230 and 232 and lugs 472 on said probe bars will enter notches 468 of the type wedges. Consequently, the probe bars 470 which engage the type wedges will rise to higher levels than the probe bars which engage the pieces of type. It is this difference in movement between the probe bars which engage the type wedges and the probe bars which engage the pieces of type that determines which U-shaped wedges 440 will be elevated to operative position.

It will be noted in Figs. 55 and 58 that an angle bar 532 is mounted intermediate bars 456 and 476 and it will also be noted that another angle bar 534 is mounted below angle bar 476. Bars 456, 476 and 534 are all fixedly secured to vertical bars 536 and crossbar 510 is also secured thereto. This arrangement maintains bars 456, 476 and 534 in fixed relationship, all of said bars occupying parallel horizontal planes and a common vertical plane. Angle bar 532, on the other hand, is slidably mounted for vertical movement in either direction on rods 538. The upper ends of said rods are secured to bar 456 and the lower ends are secured to bar 476.

Slots 540 are formed along the edge of angle bar 532 and it will be understood that these slots correspond to and register with slots 480 in bars 476 and slots 478 in bar 456. Slidably mounted in said slots 540 as in the other slots last mentioned are the probe bars 470 and also wedge pusher bars 542. These bars alternate with each other as Fig. 58 clearly shows. The lower ends of pusher bars 542 normally rest upon angle bar 534 which serves as a shelf for said pusher bars. It is by means of these pusher bars that the U-shaped wedges 440 are projected upwardly into operative position. See Fig. 55.

Pivottally mounted on angle bar 532 is a plurality of locking plates 544. These locking plates are pivotally movable about pins 546 which serve as retaining pins as well as pivoting pins to hold the locking plates in place on said angle bar 532. An expansion spring 548 is secured at one end to each of said locking plates and at its opposite end it is secured to a pin 550 that is fixed to said angle bar 532. The action of these springs upon the locking plates is to urge them to pivot in counter-clockwise direction about pins 546 as viewed in Fig. 58. A bar 552 is secured to the slotted edge of angle bar 532 by means of screws 554 and said bar 552 is maintained in spaced relation to said bar 532 in order to provide clearance for the locking plates 544 and to help support them or retain them in place on said angle bar 532 without interfering with the pivotal movement of said locking plates.

Each locking plate 544 is provided with a projecting end portion 556 on one side thereof and a projecting end portion 558 on the other opposite side thereof. Projecting end portion 558 is in the nature of a narrow finger which parallels the main body of the locking plate in spaced relation thereto. It functions in the manner of a hook, as will shortly appear, and it will hereinafter be designated either as a finger or as a hook. See Fig. 58.

It will be seen in Fig. 56 that a leaf spring 560 is secured by means of screws 562 to the side of each probe bar 470. This leaf spring has a bowed portion 564 which curves from that side of the probe bar to which the leaf spring 560 is secured to the opposite side of said probe bar. A cutout 566 is formed along one side edge of each probe bar 470 and it is through said cutout that the bowed portion 564 of leaf spring 560 curves upwardly from one side of the probe bar to the other. See Figs. 56 and 56A. Above cutout 566 is a tapered portion 568 which tapers in substantially the same direction as the leaf spring curves. The lower edge 570 of the curved portion 564 of the leaf spring is disposed in spaced relation above the lower edge 572 of cutout 566. A notch 574 is accordingly formed between edges 570 of the leaf spring and 572 of the probe bar.

Hook or finger 558 of each locking plate 544 normally engages leaf spring 560 when the probe bars are below their uppermost positions. Consequently, the locking plate is prevented from turning in counter-clockwise direction, as viewed in Fig. 58, under the action of spring 548. When one of the probe bars engages a notch 468 in one of the wedges 232, it moves upwardly to its uppermost position under the influence of spring 474. Opening 574 now registers with finger 558 in order to free the locking plate for pivotal movement in response to the pull of spring 548. This is clearly shown in Figs. 55, 59 and 58. In Fig. 55 the probe bar 470 is shown in engagement with a piece of type and consequently it is prevented from attaining its uppermost position. This is also true of two of the probe bars which are shown in Fig. 58. The probe bar which is shown in Fig. 59 and the probe bar which is situated at the right of Fig. 58 have engaged the notch of a type wedge 232 and consequently they have moved to their uppermost positions in response to the pull of springs 474 which engage them. The locking plates 544 which relate to these last mentioned probe bars are now free to pivot in counter-clockwise direction as viewed in Fig. 58 and as illustrated by Fig. 58.

Now that these last mentioned locking plates have cleared the last mentioned probe bars, they swing into engagement with the adjacent wedge pusher bars 542. See the locking plate 544 which is situated on the right side of Fig. 58. It will now be observed that each pusher bar 542 is relatively wide at its lower end and relatively narrow at its other end with a rectangular lug 576 formed a spaced distance above the wider lower end, leaving a space or notch 578 between said lug and said wider lower end. See Fig. 57 and Fig. 57A. Referring now to Fig. 58, it will be noted that when one of the locking plates 544 swings in counter-clockwise direction to the right, its projecting end portion 556 will enter and engage the space or notch 578 of the pusher bar 542 which is situated immediately adjacent thereto. The locking plate and the pusher bar will now be interlocked with each other for a reason which will shortly become apparent.

It has above been stated that the locking plates 544 are held in place on angle bar 532 by means of pins 546 about which said locking plates pivot and also by means of retaining bar 552. Consequently, locking plates 544 are locked to said angle bar 532 in the sense that relative vertical movement between said locking plates and said angle bar is prevented. It will now be seen that angle bar 532 is vertically movable between bars 456 and 476 and it is by reason of such movement that the pusher bars 542 are enabled to elevate the U-shaped wedges 440 to operative position. Reference has above been made to angle bar 532 being vertically slidably movable on vertical rods 538. More specifically, angle bar 532 is mounted at its ends on bearing blocks 580 which themselves are slidably movable on rods 538. A bearing screw 582 is secured to each bearing block and a bar 584 is piv-

totally connected to each said bearing block by means of said bearing screw 582 and a slide bearing 586 mounted in a longitudinally extending slot 588 formed in said bar 584. An adjustment plate 590 is provided on each bearing block 580 and an adjustment screw 592 engaging through a slot 594 in said plate 590 is provided to adjustably position said plate relative to said block. Bearing screw 582 is related to adjusting plate 590 so that any adjustment of said plate relative to the bearing block constitutes an adjustment of bar 584 relative to the bearing block. See Fig. 55.

It will be noted in Fig. 13 that bar 584 is pivotally secured to frame 104 by means of pin 596 on bracket 598 which is secured to said frame 104. Intermediate the ends of pivoted bar 584 is a cam follower 600 which rides in a cam track 602 formed in a cam wheel 604 which is mounted on cam shaft 276. The direction of rotation of said cam shaft is indicated by the curved arrow 606 in Fig. 13. It will be seen that the cam track has a relatively long high section 602a and a relatively short low section 602b and, of course, the transitional or transfer portions between said high and low sections.

When the cam follower 600 is in engagement with the low cam track section 602b, arm 584 is brought downwards in clockwise direction as viewed in Fig. 13 to the position which it is shown to occupy in Figs. 55 and 59. When the cam follower 600 is in engagement with the high cam track section 602a, as Fig. 13 shows, arm 584 is brought upwardly in counter-clockwise direction as viewed in Fig. 13 to the position which said bar 584 is shown to occupy in Fig. 61. Since bearing block 580 moves upwardly and downwardly with bar 584 and since angle bar 532 moves with said bearing block (there is one such bearing block at each end of angle bar 532) locking plates 544 will also be caused to move upwardly and downwardly with the angle bar, the bearing block or blocks, and arm or arms 584. Since some of the locking plates are in engagement with some of the pusher bars 542, those particular pusher bars which are engaged by said locking plates will be moved upwardly and downwardly with angle bar 532 and the other elements which are connected thereto.

Resting on top of each pusher bar 542 is a U-shaped wedge 440. When any of the pusher bars are caused to move upwardly in the manner above described, they will elevate the U-shaped wedges 440 which they support. See Fig. 61 and Fig. 62. The U-shaped wedges will be pushed upwardly into engagement with carrier bar 438. The arms of the U-shaped wedge engage said carrier bar between them and the yoke of said wedge is disposed under said carrier bar. It will be understood that while these U-shaped wedges and the carrier bar which they engage are integrally movable longitudinally of the machine as a whole, each of said U-shaped wedges is individually movable relative to each other and relative to the carrier bar, longitudinally of said bar and transversely of the machine.

Also movable relative to each other and relative to the carrier bar 438, longitudinally of said bar and transversely of the machine as a whole, are the pieces of type 230 and the type wedges 232. The type and type wedges are also movable relative to the U-shaped wedges 440 and said U-shaped wedges 440 are similarly movable relative to said type and type wedges, all such movement being longitudinally of the carrier bar once the type and type wedges and the U-shaped wedges are brought into engagement therewith.

This movement of the type and type wedges 230 and 232 respectively is controlled, to a large extent, by bellows 608 shown, for example, in Fig. 36. This bellows consists of a plurality of inter-related and interconnected sections each consisting of a pair of outer plates 610 and an inner plate 612 which is sandwiched in between the outer plates. These plates are roughly rectangular in shape as Fig. 37 clearly shows. Clips 614 secure the upper

corners of the two outer plates and the one inner plate together and corresponding clips 616 secure the lower corners of these three plates together. Side bars 618 are secured by means of screws 620 to the side edges of the intermediate plate 612 and it will be noted that these side edges and the bars 618 extend laterally outwardly from the side edges of the two outer plates 610. It will be noted that a cut-out 622 is formed in the top of all of these plates and cut-outs 624 are formed in the sides of the two outer plates. The latter two cut-outs make for a relatively narrow neck portion 626 between them and this of course renders the two outer plates quite flexible.

It will be understood that the two outer plates are made of spring metal and that they constitute, in effect, leaf springs. In their relaxed state, these outer plates are flat but they may be bowed outwardly under tension. In Fig. 48, for example, the outer plates 610 are shown bowed outwardly to a very considerable extent. In Fig. 36, for example, they are shown bowed outwardly only to a moderate extent. In Fig. 52 they are shown flat against the inner or intermediate plates 612.

It will be noted in Figs. 36 and 37 that the inner or intermediate plate 612 is provided with a downwardly extending tongue 628 and it will also be seen that a laterally extending piece 630 is formed along one side edge of said tongue 628. The downwardly extending tongue is adapted to project into a semi-circular slot 632 formed in the top and extending downwardly almost to the bottom of type wedge 232 and a corresponding slot 634 is formed in type 230 also for the purpose of receiving tongue 628. See Figs. 36, 37, 38 and 39. It will be understood that the combined thickness of each bellows section 608, that is, the inner and outer plates 612 and 610 respectively and the clips and all of its other aspects, does not exceed the thickness of the type and type wedges 230 and 232 respectively.

It will be seen in Figs. 44, 45 and 46 that the tongue 628 of each bellows section projects through slot 384 formed in the pivoted type aligners 372. Consequently, when the type aligners vertically align the type and type wedges as above described, tongues 628 will be positioned and poised for entry into slots 632 and 634 of the type wedges and type pieces respectively. It will be understood from the foregoing that tongues 628 are vertically movable downwardly into engagement with these slots 632 and 634 and it will also be understood that they are movable upwardly out of engagement with said slots.

The means for moving tongues 628 vertically into and out of engagement with the slots in the type and type wedges 230 and 232 respectively is shown in Figs. 8 and 36. It will be noted in Fig. 36 and also in Fig. 37 that a central hole is formed in the inner and outer plates of each bellows section 608 to accommodate a rod 636 which extends transversely of the machine as a whole. This rod 636 projects through openings 638 in blocks 640, there being two such blocks, one on each side of the machine, that is, one at each end of rod 636. Each block 640 is supported by an upright 642 which itself is supported on bar 438 mounted on slide 646. There are, of course, two such slides, one on each side of the machine, and it will hereinafter be seen that these slides are important elements in the transfer mechanism by which the type and type wedges 230 and 232 and the U-shaped wedges 440 are moved into and out of operative positions. A set screw 648 in block 640 engages upright 642 and it is by this means that the block may be adjustably secured to the upright, said upright in the illustrated form of the invention projecting through a vertical hole in said block. It is by this means that each block 640 may be adjustably positioned relative to slide 646.

Referring now to Figs. 35 and 36 it will be seen that a tubular externally threaded plug 650 is screwed into a tapped vertically extending hole 652 formed in each block 640. A pin or peg 654 projects through tubular plug 650

and through a hole 656 formed in the end of rod 636. Rod 636 is free to move vertically relative to pin 654 but it cannot move horizontally relative thereto and it will be understood that it is this pin which prevents longitudinal dislodgment or shifting of said rod 636. There are, of course, two such pins 654, one at each end of rod 636. Mounted on each of these pins is a compression spring 658 which bears upwardly against plug 650 and downwardly against rod 636. It will be apparent that this spring acts to urge rod 636 downwardly as far as it will go and since the bellows sections are all mounted on said rod 636, the action of the spring is to urge said bellows and especially the downwardly extending tongues 628 in downward direction to bring these tongues into engagement with slots 634 and 632 in the type and type wedges.

The means for elevating rod 636 against the action of springs 658 in order to disengage tongues 628 from the type and type wedges includes a vertically extending rod 660 which is slidably mounted for vertical movement in a hole 662 formed in each slide 646 and a registering hole 664 formed in each block 640. The upper end of rod 660 abuts rod 636 and the lower end is free. A collar 666 on each rod 660 engages the top of carrier bar 438 to limit the downward movement of each said rod. See Fig. 36. It will be noted at this point that the two ends of carrier bar 438 are mounted on and secured to the two slides 646 so that any movement of the slides forwardly and backwardly on the machine causes a corresponding movement of the carrier bar 438 and everything that the carrier bar carries and it also causes a corresponding movement of rod 636 and the entire bellows mechanism.

Fig. 8 shows slide 646 in an advanced position. In this position, rods 660 and cross rod 636 are moved downwardly as far as they will go and tongues 628 are in engagement with the type and type wedges. It will be observed that another vertically extending rod 668 is mounted on each side of the machine for vertical movement both upwardly and downwardly. The upper end of each rod 668 is slidably mounted in a bearing block 670 which is secured to the top of frame 104. The lower end of each rod 668 is pivotally connected by means of a yoke 672 and a pin 674 to one end of an arm 676. The opposite end of said arm is pivotally secured to frame 104 by means of a bolt 678. Intermediate the two ends of bar 676 is a bracket 680 which carries a cam follower 682. This cam follower engages a cam 684 which is mounted on cam shaft 276. Arrow 686 indicates the direction of rotation of said cam shaft and said cam.

It will be seen in Fig. 8 that cam 684 has a relatively small high cam face 684a and a relatively long low cam face 684b. When the cam follower 682 is in engagement with the low cam face 684b, as shown in Fig. 8, arm 676 and rod 668 will be situated in their lowermost positions. When the cam follower engages the high cam face 684a, arm 676 will be swung upwardly in clockwise direction about the axis of bolt 678 and rod 668 will be moved upwardly from its Fig. 8 position. It will be noted that a bracket 688 is adjustably secured to rod 668 by means of set screw 690. When slide 646 is in its rearmost position, bracket 688 will register with the lower end of rod 660. Consequently, when rod 668 is moved upwardly as above described, bracket 688 will push rod 660 upwardly against the action of spring 658. Since rod 660 is in engagement with rod 636, this will have the effect of raising bellows 608 and particularly tongues 628 of said bellows out of engagement with the type and type wedges. When the cam follower 682 once again engages the low cam section 684b, arm 676 and rod 668 will move downwardly and bracket 688 will free rod 660 for downward movement under the action of spring 658 as far as collar 666 will allow it to go. Rod 636 will once again move downwardly together with bellows 608 and

tongues 628 will re-engage the type and type wedges. This action occurs at both ends of rod 636.

It has been stated that slide 646 moves forwardly and backwardly. Referring now to Figs. 35 and 36 it will be observed that slide 646 is provided with a groove 692 which extends horizontally thereof along its inner side. This groove accommodates a horizontal plate 694 which is supported on the top of frame 104. The edge of plate 694 which projects into groove 692 serves as a track for said slide 646 and the slide is movable along said track both forwardly and backwardly. Fig. 36 shows only one side of the machine and a corresponding construction appears on the opposite side thereof. Slide 646 is also provided with a horizontally extending flange 696 along its top edge, said flange projecting laterally inwardly toward the center of the machine. This flange rides atop a horizontally extending plate 698 which may be considered to constitute the table top of the machine. This table top 698 rests on plate 694 and both are therefore supported on frame 104. It is to flange 696 that carrier bar 438 is secured and on which it is mounted.

The mechanism which causes the two slides 646 to move forwardly and backwardly is shown in Figs. 1 and 2. It will there be seen that a shaft 700 is supported by bearings 702 on frame members 242 of main frame 102. Secured to each end of shaft 700 is a wheel 704 which may be considered to be a crank wheel. Also secured to said shaft is a gear wheel 706 which is engaged by a gear chain 708. Said gear chain also engages a gear wheel 710 on the shaft of reduction gears 712 of motor 714. This motor is mounted on brackets 716 which are secured by means of bolts 718 to frame 106 and by means of brackets 720 to frame 102. When this motor is in operation, it drives shaft 700 at a relatively low rotational speed and crank wheels 704 will turn with said shaft at the same relatively low speed. A bracket 722 is secured to each wheel 704 and a crank pin 724 is secured to each said bracket. A rod 726 is pivotally secured at one end to each crank pin 724 and it is pivotally secured at its opposite end to a similar pin 728 secured to each slide 646. It will be understood from the foregoing, that rods 726 serve as crank rods between the crank wheels 704 and slides 646. When motor 714 is in operation and the crank wheels are in rotation by reason thereof, rods 726 will act upon slides 646 to thrust them forwardly and then pull them backwardly in synchronization with all of the other operations of the machine.

It will be recalled that when the type and type wedges 230 and 232 are pushed out of the type rings and on to the carrier bar 438, the forward movement of said type and type wedges is arrested by horizontal stop rods 304 which are supported by crossbar 306. These horizontal stop rods and their supporting crossbar constitute not only stop members as above indicated but they also constitute what may be described as the push back comb of the machine by which the type and type wedges are returned to their proper places in the type rings. It will be understood from the foregoing, that after the type and type wedges are moved forwardly and brought to a stop on carrier bar 438 by the rods 304 of the push back comb, before said type and type wedges and their carrier bar can be moved forwardly to their respective operative positions, it is necessary to move said push back comb out of the way of said type and type wedges and said carrier bar.

Figs. 17 and 18 show that the push back comb consisting of rods 304 on bar 306 is movable in four directions, that is, downwardly, upwardly, forwardly and backwardly. When the push back comb is in its upper forward position, it serves solely as a series of stop members to limit the forward movement of the type and type wedges out of the type rings. It is necessary for the push back comb to move downwardly and out of the way of the type and type wedges and the carrier bar which supports them in order to allow said type and type wedges and

said carrier bar to move to operative positions at the forward end of the machine. Similarly, it is necessary for the push back comb to remain in its lowermost position in order to allow the type and type wedges and the carrier bar to move backwardly on the return trip of the type and type wedges back to the type rings. Once the type and type wedges and the carrier bar clear the push back comb on said return movement, the push back comb must once again move upwardly until it resumes its upper forward position for re-engagement with the type and type wedges. The push back comb must then move backwardly in order to push the type and type wedges back into the type rings. The push back comb will then move forwardly to await the next group of selected type and type wedges and this process is repeated for each line of type.

The mechanism for moving the push back comb downwardly out of the way of the type and type wedges and the carrier bar is shown in Figs. 14, 17 and 18. It will be seen that bar 306 of the push back comb is mounted on a plate 730 which, in turn, is mounted on a pair of slides 732, one at each end. These slides are mounted for slidably movement forwardly and backwardly of the machine on plates 734. Plates 734, in turn, are mounted on brackets 736 which themselves constitute a pair of vertical slides. Similarly mounted on plates 734 are supports 738 for guide bar 309 above mentioned. This guide bar has a plurality of holes formed therein to accommodate rods 304 of the push back comb. These rods are longitudinally slidably movable in said guide bar holes so as to engage in the forward and backward movements above mentioned. Guide bar 309 is also provided with a plurality of vertically extending lugs 740 which serve as stop members or guides for the type and type wedges as shown, for example, in Fig. 42. More particularly, bar 306 of the push back comb is mounted on supports 742 which themselves are mounted on plates 730 and guide bar 309 is mounted on a bar 744 which itself is mounted on supports 738 on plate 734. See Fig. 43.

Vertical slide brackets 736 are slidably mounted on vertically extending rods 746 and it will be noted that the upper ends of rods 746 are secured to the table top 698 and to plate 694 below said table top. It will also be noted that the lower ends of said rods 746 are secured to frame 104 by means of brackets 748. See Figs. 14 and 17. It will be understood from the foregoing that these vertical rods 746 are stationary rods which perform their functions passively rather than actively.

It will be noted in Fig. 18 that an elongated slot 750 is formed in plates 730 to accommodate rods 746. Consequently, plates 730 are free to move both horizontally and vertically relative to rods 746. Plates 734, on the other hand, are provided with a small hole 752 which is just large enough to accommodate the rods 746. Consequently, plates 734 are free to move vertically on said rods but not horizontally relative thereto.

A compression spring 754 is mounted upon each rod 746. A collar 756 is secured to each rod to support the lower end of each spring 754. The upper end of the two springs bears up against slide brackets 736 and the action of these springs is simply to help support the weight of brackets 736, plates 734, slides 732, plates 730 and the entire push back comb structure above described. See Figs. 14 and 17. It will be noted that a plate or bar 758 is adjustably secured to each slide bracket 736 by means of a set screw 760. A link 762 is pivotally secured at its upper end to each bar 758 by means of a screw 764 and it is pivotally secured at its lower end to one end of a bar 766 by means of a pin 768. The opposite end of bar 766 is pivotally secured by means of pin 770 to bracket 772 on frame 104. See Fig. 14.

It will be noted, also in Fig. 14, that a cam follower 774 is mounted on each bar 766 intermediate its ends. This cam follower is in engagement with cam track 776 of cam 778. This cam is mounted on cam shaft 276 and

its direction of rotation is indicated by arrow 780. Cam track 776 has two main sections: A low track section 776a and a high cam track section 776b. When the cam follower is in engagement with the low cam track section 776a, arm 766 will occupy its lowermost position and link 762 will bring slide bracket 736 and everything supported thereby, including the push back comb, downwardly to a position which would clear the carrier bar 438 and the type and type wedges mounted thereon. This is shown in Fig. 14. When the high cam track section 776b is brought into engagement with cam follower 774, arm or bar 766 will be caused to swing upwardly in counter-clockwise direction as viewed in Fig. 14 about its pivot 770. This will cause link 762 to rise and to carry with it slide bracket 736 and everything supported by said bracket including the push back comb. This upward movement will be assisted by the action of spring 754.

The foregoing relates to the vertical movement of the push back comb structure. The horizontal movement of the push back comb is effected by the mechanism shown in Figs. 9, 17 and 18. It will be seen that a vertically extending bar 782 is pivotally secured at its lower end by means of bolt 784 to each side of frame 104. At the upper end of each bar 782 is a vertically elongated slot 786. A slide or bearing 788 is slidably movable in slot 786 and a screw 790 secures said slide to a bar 792. This bar is secured by means of screws 794 to slide 732 above mentioned. More particularly, there are two such slides 732 and consequently two bars 782 and two slides or bearings 788.

Intermediate the ends of each bar 782 is a cam follower 796 and it will be noted that this cam follower engages a cam track 798 in cam wheel 430. This cam wheel rotates in the direction of arrow 360. There are two main cam track sections in cam track 798: The first is the larger track section 798a which constitutes the low cam track section and the other is the very small high cam track section 798b. When the cam follower 796 is in engagement with the low cam track section 798a, bar 782 will be in its rightwardly inclined position as viewed in Fig. 9. Slide 732, plate 730 and the push back comb 304, 306 will accordingly occupy their forwardmost positions and this irrespective of their relative vertical positions. Slot 786 in bar 782 permits of such vertical movement irrespective of the horizontal positions of these elements. When cam follower 796 engages the high cam track section 798b, bar 782 will assume its leftwardly inclined position as viewed in Fig. 9. This will cause slide 732 to move backwardly on plate 734 and to carry with it plate 730 and the push back comb. This is done when the push back comb is in its upper position and the object of such movement is to push the type and type wedges 230 and 232 respectively back into the type rings. See also Fig. 70.

After the push back comb is moved downwardly out of engagement with the type and type wedges, said type and type wedges and the carrier bar 438 which supports them are free to move forwardly to operative positions at the front end of the machine. The mechanism for moving the carrier bar and the type and type wedges forwardly and also for moving them backwardly has above been described in connection with crank wheels 704 and crank arms or rods 726 as shown in Fig. 2 and in Fig. 1. It will be understood that as such forward movement takes place, the type and type wedges are brought close together and as such backward movement takes place the type and type wedges are moved apart. The type and type wedges are moved together to the length of a single line of type. They are moved apart to correspond to the spacing of the type and type wedge slots in the type rings from which the type and type wedges which are selected for a given line of type have been drawn.

The means for moving the type and type wedges toward each other on the forward movement of the carrier

bar and for moving them away from each other on the backward movement of the carrier bar comprises a pair of slots or tracks 802 which are shown in their entirety in Fig. 1, a pair of rollers 804 in said track slides 802 and a pair of slides 806 which support said rollers. See Figs. 36 and 42. It will be noted that track slots 802 are formed in the table top 698 and that these slots converge in forward direction, that is, they are relatively wide apart at the back end of the table top and relatively close together at the front end of the table top. The back ends 802a of the two track slots 802 curve inwardly out of alignment with the converging portions of said slots to form two parallel portions which extend longitudinally of the machine. Similarly, the two front ends 802b of said track slots 802 curve outwardly out of alignment with the converging portions of said slots to form two parallel portions which also extend longitudinally of the machine. See Figs. 1 and 7.

Slides 806 are slidably mounted on carrier bar 438 with enough clearance for bar 436 on said carrier bar. These slides are movable toward and away from each other along said carrier bar and they are compelled to move toward each other when the carrier bar is moved forwardly on the machine since track slots 802 would compel such movement by reason of their engagement with rollers 804. Similarly, backward movement of the carrier bar would cause slides 806 to move away from each other, also by reason of the engagement of rollers 804 with track slots 802. The mechanism for causing the carrier bar to move forwardly and backwardly has above been described in connection with crank wheels 704 and crank rods 726. See Figs. 1, 2 and 70.

It will be noted in Figs. 36 and 48 that secured to the top of slides 806 by means of screws 808 are vertically extending plates 810. These plates are provided with elongated openings 812 through which rod 636 extends. Since these openings are elongated, rod 636 is free to move upwardly and downwardly, as above described, to move the bellows 698 upwardly and downwardly to disengage and engage the type and type wedges with the downwardly extending tongues 628. Slidably mounted on slides 806 and plates 810 are channel-shaped plates 814. These channel-shaped plates 814 are mounted for vertical movement relative to slides 806 and plates 810 but they are not free to move in any other direction relative to said slides 806 and said plates 810. A hole is formed in each channel-shaped plate 814 to accommodate rod 636 but this hole is not elongated in the sense that opening 812 is elongated but rather it snugly accommodates rod 636 precisely in the same manner that the corresponding holes in the bellows accommodate said rod. Since these holes last mentioned are co-extensive, so to speak, with rod 636, they are difficult to show in the drawing. However, Fig. 48 will be used to show hole 816 in channel plate 814, corresponding holes 818 in outer plates 610 of the bellows and holes 820 in inner plates 612 of the bellows. Consequently, when rod 636 is moved vertically in either direction, channel plate 814 and the bellows 698 will move in the same direction with it.

Channel plate 814 is secured to the outer plate 610 of the bellows which it abuts. When the carrier bar moves forwardly, slides 806 will move inwardly toward each other and channel plates 814 on the two slides will press against both ends of the bellows to compress the bellows from their expanded condition as shown in Fig. 48, for example, to their tightly compressed condition as shown in Fig. 63. Conversely, when the carrier bar moves backwardly, slides 806 will move outwardly and away from each other and channel plates 814 will pull the bellows back to expanded condition as shown in Fig. 48. It has above been stated that outer plates 610 of the bellows are made of spring metal and that in their normal relaxed condition they are flat rather than bowed. The action of the bellows would accordingly be toward con-

traction rather than expansion and this would assist slides 806 in their inward movement to compress the bellows to their small proportions as shown in Fig. 63. The outward or expansion movement of the bellows would, in such case, be opposed to the normal tendency of the bellows to assume a contracted position. It should be understood, however, that the bellows may be constructed in reverse fashion, that is, with outer plates 610 which are normally bowed in their relaxed condition as, for example, shown in Fig. 48. In such case, the bellows would tend to expand by reason of the inherent spring tension in the bowed outer plates. The inward action of slides 806 would be in opposition to this spring action and the outward movement of said slides 806 would be with the aid of said spring action.

Provision is made to assist in uniformly spacing the individual sections or segments of the bellows on the backward movement of the carrier bar 438. This means is best shown in Figs. 36, 48 and 70. It consists of a plurality of nested U-shaped strips 822, 824 and 826 respectively. The yokes of these U-shaped strips rest one upon the other and they occupy parallel horizontal planes. They project through cut-outs 622 formed in the top portions of the plates which constitute the bellows and through corresponding cut-outs 828 in channel plates 814 and cut-outs 830 in plates 810. Crossbars 832 on channel plates 814 prevent these strips from coming out of the cut-outs last above mentioned. Slidable movement of these strips, relative to each other and longitudinally of rod 636 is, however, provided for as a comparison of Figs. 36 and 48 will clearly show. The outer legs 822a, 824a and 826a project downwardly and rest upon rod 636. It will be noted in Fig. 70 that there are small recesses or cut-outs in these legs to accommodate the rod. The inner ends or legs 822b, 824b, and 826b engage the bellows sections at equally spaced intervals. These strips 822, 824 and 826 perform no function insofar as compressing the bellows is concerned but when expansion of the bellows takes place, the engagement of these strips with the individual sections or segments of the bellows helps to spread them uniformly and this action takes place, as shown in Fig. 48, when legs 826a (there are two sets of strips, one on each side of the machine) engage stop members 834 on rod 636. Leg 824a then engages leg 826a and leg 822a then engages leg 824a, on each side of the machine. This causes legs 822b, 824b and 826b to spread out even beyond their positions as shown in Fig. 7. When the bellows is contracted, as above described, legs 822b, 824b and 826b are brought relatively close together while legs 826a, 824a and 822a are moved relatively wide apart. Consequently, there is no interference with the compression action and movement of the bellows.

It will be recalled that there are two types of wedge in the present invention, the first type being the passive wedge 232 and the second type being the active U-shaped wedge 440. Wedges 232 are mounted on and carried by the carrier bar 438 side by side with the pieces of type 230. But the U-shaped wedges 440 simply engage the carrier bar between their respective arms 444 and 446. Provision must be made for supporting these U-shaped wedges 440 in elevated positions, else they would disengage the carrier bar 438.

When the U-shaped wedges 440 are raised to their elevated positions by pusher bars 542, as shown, for example, in Fig. 47, these pusher bars are the only means of supporting the U-shaped wedges in their elevated positions until such time as the forward movement of the carrier bar 438 commences. Since the pusher bars are left behind, other means must be provided to retain the U-shaped wedges in their elevated positions without interfering with their movement both forwardly and backwardly with the carrier bar and also laterally along the carrier bar and, as will also appear, the U-shaped wedges

must also be free in their forwardmost positions to engage in vertical movement.

It will be seen in Figs. 1, 63 and 70 that table top 698 has a substantially triangular opening 836 formed therein, centrally thereof, its sides being substantially parallel to track slots 802 of said table top. Within said triangular opening are the means whereby the U-shaped wedges 440 are supported after they leave the pusher bars 542. It will be seen in said Figs. 1, 63 and 70, that a plurality of tracks are situated within said triangular space or opening 836. Each track consists of three sections: The rearmost section is identified by the reference character 838a, the intermediate section is identified as 838b and the forwardmost section is identified as 838c, each entire track being identified by the reference character 838. Between adjacent tracks 838 are slots 840. These tracks and the slots between them are parallel, generally, to track slots 802 in the table top. In other words, the major portion of each track 838 and each adjacent slot 840 converges toward the front center of the table top from its back end. The rearmost end of each track 838 and slot 840 is longitudinally aligned with the adjacent type ring, the rearmost ends of all of the tracks and slots being parallel to each other. Similarly with the front end of these tracks 838 and slots 840: they too are parallel to each other and to the longitudinal axis of the machine. It will be understood that the drawing shows only a few of these tracks 838 and slots 840 and similarly the drawing shows only a few of the type rings. It will be understood that this is done solely for clarity and there are as many type rings as a machine of this kind would require. For each type ring there is a track 838 and for each space between type rings there is a slot 840. Viewing Fig. 1, for example, it will be understood that the entire space between the two groups of four type rings shown therein is occupied by additional type rings. Similarly, the entire space between the two groups of four tracks is filled with additional tracks, the total number of tracks corresponding to the total number of type rings.

Since the tracks converge from a space corresponding to the total width of all of the type rings to a space corresponding to the length of a single line of type, the tracks must necessarily be wider at their back ends and narrower at their front ends and it will be seen that they taper gradually and uniformly from their wide back ends to their narrow front ends. It will also be understood that while it is necessary for the outer tracks to converge inwardly toward the front of the machine, the innermost tracks will simply follow a straight or substantially straight line extending longitudinally of the machine. See Fig. 1. The angle at which tracks 838 converge toward the front center of the machine will be determined by the position of said tracks. The outermost tracks will converge at a sharper angle than those which are positioned nearer the center of the machine and this is also true of slots 840 which separate them. Track sections 838a are fixed in the sense that they do not move laterally either toward or away from each other. Similarly track sections 838b. Track sections 838c, on the other hand, are pivotally movable about pivots 842 at their back ends so as to enable their forward ends to swing to a slight extent toward and away from each other. See Fig. 70.

It will be noted in Fig. 17 that a plate 844 is mounted on push back comb bar 306 and it will be seen in Fig. 43, for example, that this plate is also supported on guide bar 309. Track sections 838a are mounted on plate 844. It has above been indicated that bars 306 and 309 are vertically movable and it will now be understood that track sections 838a are similarly vertically movable with said bars 306 and 309. When these bars 306 and 309 are elevated to their Fig. 43 positions, rods 304 are aligned with the type and type wedges

to serve as stop members relative thereto. When bars 306 and 309 are moved downwardly to their Fig. 70 positions, track sections 838a occupy a common horizontal plane with track sections 838b. It will be understood that track sections 838b are always situated on the same horizontal level. It is at this level that all of the track sections above mentioned may serve as supports for the U-shaped wedges 440. See for example, Figs. 36 and 37 where it will be seen that the U-shaped wedges 440 are supported on track sections 838b. Pins 450 which project downwardly from said U-shaped wedges project into slots 840 between said track sections. It is these pins in these slots which guide the U-shaped wedges 440 in their movement forwardly and backwardly with carrier bar 438. The track sections support the U-shaped wedges and the slots guide them. It will be seen in Figs. 36 and 37 that track sections 838b are supported on plate 694, above mentioned, and it will be understood that this plate corresponds to plate 844 in the sense of its constituting a support for the track sections.

Reference to Fig. 70 will disclose the fact that slots 840 are provided with relatively wide ends 840a at the back ends of track sections 838a. These widened portions serve as approaches to the slots to facilitate entry of pins 450 into said slots. The action is simply as follows: When track sections 838a are moved downwardly to a common horizontal plane with track sections 838b, slots 840 between the tracks of the two sections will become aligned with each other to form continuous slots capable of guiding pins 450. Forward movement of carrier bar 438 will cause the U-shaped wedges 440 to ride up upon track sections 838a and the rounded or beveled bottom edge of said U-shaped wedges as shown in Figs. 40 and 37 will facilitate such movement. By the same token, pins 450 will be brought into slots 840 and the U-shaped wedges will be adequately supported and guided in their forward movement.

The U-shaped wedges 440 will move with the carrier bar 438 and the type and type wedges 230 and 232 respectively forwardly toward the front of the machine and all the while these U-shaped wedges will be supported on tracks 838 and the pins 450 of said U-shaped wedges will ride within and along slots 840 between said tracks. When track sections 838c are reached, however, a new movement of the U-shaped wedges 440 takes place. Similarly, a new mechanism takes over the task of accurately positioning and tightly holding the type and type wedges preparatory for the reproduction process.

It will be seen in Fig. 70 that an angle bar 846 is secured in fixed vertical relation to the track sections 838c, said track sections being free to swing about their respective pins 842 on a common horizontal plane, relative to each other and relative to said angle bar 846. It will be noted in Fig. 49 and in Fig. 50 that this angle bar 846 is supported by means of lugs or brackets 848 on crossbar 850. The horizontal portion of this angle bar is situated at precisely the right level relative to tracks 838c to engage slot 448 of the U-shaped wedges 440. See Fig. 49 which shows partial engagement of said angle bar 846 with said slot 448 and see Fig. 51 which shows complete engagement thereof.

Angle bar 846 now controls the vertical positioning and movement of the U-shaped wedges 440. It will be seen in Fig. 15 that bar 850 is mounted on slides 852 which are movable forwardly and backwardly on rods 854. Secured to said slides is another angle bar 856 which prevents relative movement between the slides and also performs other functions. Rods 854 are secured at their back ends to vertical bars 858 and to a crossbar 860 which is fastened to the upper ends of said vertical bars 858. Crossbar 860 holds these vertical bars 858 and the two rods 854 against movement rela-

tive to each other. See Fig. 49. It will also be seen in Fig. 49 that each vertical bar 858 is pivotally secured at its lower end by means of pin 862 to an arm 864. The back end of said arm 864 is pivotally secured by means of pin 866 to a vertical rod or bar 868 which is fixed to frame 104. Similarly, another arm 870 is pivotally secured at its back end to vertical bar 868 by means of pin 872 and it is secured at its forward end by means of pin 874 to vertical bar 858. Arms 870 and 864 are parallel to each other and bar 868 is aligned vertically as is bar 858 when the two arms 870 and 864 are horizontally positioned. Consequently, arms 870 and 864 may be swung either upwardly or downwardly on their respective pivots without disturbing the vertical alignment of bar 858. In other words, said bar 858 will always remain vertical although it may be shifted either upwardly or downwardly on arms 870 and 864. Compare Figs. 49 and 51 and see also Fig. 53. In all three cases, arms 870 and 864 occupy different angular positions about their respective pivots 872 and 866 but in all cases bar 858 is maintained in a perfectly vertical position. It will of course be understood that there are two sets of these arms 870 and 864 and two bars 858, one set and one bar on each side of the machine.

It will be recalled that rods 854 are secured to bar 860 and bars 858. These rods 854 occupy a common, horizontal plane when bars 858 occupy a common vertical plane. Since bars 858 always occupy a vertical plane for the reasons above given, rods 854 will also always occupy a common horizontal plane. However, the vertical movement of arms 870 and 864 and rods or bars 858 will change the horizontal plane on which rods 854 are disposed but whether said rods 854 move upwardly or downwardly, they will always extend horizontally. Again compare Figs. 49, 51 and 53 where it will be seen that although rods 854 occupy different vertical levels they always occupy a horizontal plane.

It will be noted, for example in Fig. 15 and also in Fig. 49, that trunnions 876 are connected to blocks or slides 852 and that said trunnions engage downwardly sloping slots 878 formed in side plates 880 secured to the forward end of frame 104. Slots 878 are cam slots which carry trunnions 876 downwardly upon their forward movement and cause said trunnions to move upwardly on their backward movement. Since the trunnions are connected to slides 852, and since said slides are movable longitudinally only on rods 854, the consequence of such downward forward movement of trunnions 876 is to cause slides 852 to move downwardly and forwardly and rods 854 to move downwardly to the positions of said parts illustrated in Fig. 51. Since angle bar 846 moves integrally with slides 852, it also moves forwardly and downwardly and carries the U-shaped wedges 440 along with it. These wedges are now ready for the wedging action which must take place in order to properly justify and securely hold the type and type wedges 230 and 232 respectively.

It will be noted, for example in Fig. 15 and also in Fig. 49, that trunnions 876 are connected to blocks or slides 852 and that said trunnions engage downwardly sloping slots 878 formed in side plates 880 secured to the forward movement of the U-shaped wedges takes place it is necessary to lock the type and type wedges 230 and 232 respectively against any vertical movement whatsoever but they must nonetheless remain relatively free to engage in the slight lateral movement which the upward action of the U-shaped wedges 440 is bound to cause.

Reference is here made to U-shaped supports 882 which are best shown in Fig. 70 and also to cam 884 which is shown in Figs. 49, 51 and 53. U-shaped supports are mounted on the upper ends of rods 886. The lower ends of these rods are pivotally secured to bar 888 by means of pins or screws 890. Bar 888 is mounted

on an angle bar 892 which is secured to the front end of frame 104. It will be noted in Fig. 70 that the upper ends of rods 886 project through blocks 894 which are pivotally movable about the central axis of trunnions 876. As a matter of fact, blocks 894 and trunnions 876 may be integral with each other, in which case they must both be pivotally movable relative to slides 852, or said trunnions may be fixed to said slides and blocks 894 may then be angularly movable on said trunnions. In either case, blocks 894 are free to pivot about the axis of said trunnions. Similarly, said blocks 894 are free to move longitudinally of rods 886 and such movement takes place first downwardly and then upwardly as will shortly appear.

Referring once again to Fig. 70, it will be seen that rods 886 occupy inclined positions wherein their upper ends are rearward of their lower ends. The U-shaped supports 882 are now in position to engage carrier bar 438 on the forward movement of said bar. The carrier bar engages the higher of the two arms of said U-shaped supports 882, as viewed in Fig. 70, and continued forward movement of the carrier bar brings it in between the two arms of said U-shaped supports. Once the carrier bar 438 engages the U-shaped supports 882, continued forward movement of the carrier bar causes said U-shaped supports and rods 886 on which they are mounted to move forwardly from their Fig. 70 positions to their Fig. 52 positions wherein said rods 886 are vertically positioned. As rods 886 swing forwardly under the influence of the forwardly moving carrier bar 438, the entire assembly which supports the U-shaped wedges 440, including angle bar 846 and bar 850, angle bar 856 and slides 852, will move forwardly with said rods 886. Simultaneously, downward movement of angle bar 846, bar 850, angle bar 856, slides 852, track sections 838c, and the U-shaped wedges 440 themselves, will take place by reason of the engagement of trunnions 876 with cam slots 878. When the type reproduction process is completed and the carrier bar 438 is caused to move backwardly, rods 886 will swing backwardly with said carrier bar to their Fig. 70 positions and the several components last mentioned, including angle bar 846 and U-shaped wedges 440 will be caused to move upwardly and backwardly under the combined influence of the backwardly moving carrier bar and the inclined cam slots 878.

When the carrier bar 438 reaches its forwardmost position, cam 884 is actuated to clamp said carrier bar and the slides 806 which are mounted thereon in fixed operative positions. Actually, there are two such cams, one on each side of the machine. It will be noted in Figs. 12 and 70 and also in Figs. 49, 51 and 53, that cams 884 are fixed to a shaft 896 which is journaled into supports 898 mounted on table top 698. Arms 900 are fixed at one end to said shaft 896 and they are pivotally secured at their opposite end to rods 902 by means of pins 904. The lower ends of rods 902 project through plates 906 on arms 908. A collar 910 on rods 902 prevents upward movement of plates 906 relative to said rods 902 beyond the limit fixed by said collar. Below plates 906 are compression springs 912 which bear upwardly against said plates and downwardly against nuts 914.

It will be noted in Fig. 12 that arms 908 are pivotally secured by means of pins 916 to bars 506 previously mentioned in connection with Fig. 11. Intermediate the ends of arms 908 are cam followers 918 which engage cam tracks 920 in cam wheel 922. This cam wheel is mounted on cam shaft 276 and the direction of rotation of said cam shaft and cam wheel is indicated by the curved arrow 924 in said Fig. 12. Cam track 920 has a relatively small low cam section 920a and a relatively long high cam section 920b. When cam follower 918 is in engagement with the high cam track section 920b, arms 908 will occupy their Fig. 12 positions which represent the upper limits of their travel. When cam follower

918 engages the low cam track section, arms 908 are pulled downwardly against springs 912. Since these springs abut nuts 914 on rods 902, the effect will be to pull said rods 902 downwardly and thereby to move arms 900 and shaft 896 in counter-clockwise direction as viewed in Fig. 12 and in clockwise direction as viewed in Figs. 51 and 70. Since cams 884 are fixed to shaft 896, these cams will also be caused to turn in the same direction.

It will now be noted, particularly in Figs. 49 and 70, that a bar 926 is supported at its ends on carrier bar 438 by means of studs 928. There is clearance between bars 926 and 438, sufficient to clear the upper shoulder 930 of slides 896. Slides 896 are normally free to move longitudinally both of carrier bar 438 and bar 926 last mentioned. It will also be noted that the type and type wedges 230 and 232 respectively are disposed between said bars 438 and 926 during the movement of said bar 438 forwardly and backwardly of the machine. Bar 926 is similarly movable with carrier bar 438. When cams 884 are actuated by the means last above described in connection with Fig. 12, they engage bar 926 as is clearly shown in Fig. 53 and said bar is clamped downwardly as rigidly as the tension of springs 912 will permit.

One last operation is required in order to justify and lock the type and type wedges preparatory to the type reproduction operation. Reference is here made to the upward movement of the U-shaped wedges 440 from their Fig. 51 positions to their Fig. 53 positions. This upward movement of the U-shaped wedges is effectuated by the mechanism which is shown in Fig. 15. It will be seen that arms 932 are pivotally supported by means of pins 934 at the back end of frame 104. At their forward ends arms 932 are provided with longitudinally extending slots 936 in which slides 938 are slidably disposed. Screws 940 secure these slides 938 to a frame 942 as Fig. 70 clearly shows. Frame 942 is mounted for vertical slideable movement on vertical rods 944. The lower ends of these rods 944 are secured to bar 888 and the upper ends are secured to the table top 698. Compression springs 946 on rods 944 between frame 942 and bar 888 supports said frame and urge it upwardly.

Arms 932 control the vertical movement of frame 942. It will be seen in Fig. 15 that a cam follower 948 is mounted on each arm 932 intermediate its ends. This cam follower rides in a cam track 950 formed in cam wheel 952. This cam wheel is secured to cam shaft 276 and curved arrow 934 indicates the direction of rotation of said cam shaft and cam wheel as viewed in Fig. 15. Cam track 950 has a long, low cam track section 950a and a very short high cam track section 950b. When the cam follower 948 is in engagement with the low cam track section 950a, arm 932 will be in its downward position as shown in Fig. 15. When cam follower 948 is in engagement with the high cam track section 950b, arm 932 is thrust upwardly to its uppermost position and causes frame 942 to move upwardly with it.

Extending through frame 942 is a pair of vertically extending rods 956 which are vertically movable relative to said frame. A crossbar 958 is secured to the lower ends of said rods 956 by means of screws 960. It will be seen in Figs. 50 and 52 that crossbar 958 abuts the bottom of frame 942 when said frame is in its lowermost position. This is so because compression springs 962 are mounted on rods 956 above said frame 942 and said springs bear downwardly against said frame 942 and upwardly against a crossbar 964 which is secured by means of screws 966 to the top ends of rods 956. Springs 962 push upwardly against bar 964 and thereby urge rods 956 and bar 958 upwardly.

Secured to bar 964 is a pair of angle plates 968 whose horizontal portions project across the top of said bar 964 in spaced relation thereto. See Figs. 50 and 70. When bar 830 and angle bar 846 and U-shaped wedges

440 are brought forwardly and downwardly to their Fig. 51 positions, said bar 830 is situated immediately above angle plates 968, angle bar 856, and more particularly its horizontal portion, projects into the space between frame 964 and the horizontal portion of plates 968. See Fig. 51. It will be understood that at this moment trunnions 876 are free of cam slots 878. See Fig. 70 where it will be seen that these cam slots 878 are open at their lower ends.

When arms 932 are moved upwardly by the mechanism shown in Fig. 15, frame 942 is moved upwardly with said arms and angle bar 856 is moved upwardly with said frame. See Figs. 53 and 54. This causes bar 850 to move upwardly with angle bar 856 and angle bar 846 and U-shaped wedges 440 move upwardly with said bar 850. The tension of springs 962 will determine the pressure which bar 964 will exert in upward direction and the tension of said springs will thereby also determine the pressure under which U-shaped wedges 440 are forced upwardly in engagement with tapered cam faces 452 and 454 of type wedges 232. The type and type wedges will now be fully justified and locked in operative positions in complete readiness for the reproduction process.

When the reproduction process or operation is completed, the entire procedure above described is reversed in order to return the type and type wedges to the type rings and the U-shaped wedges to the magazine which stores them. The U-shaped wedges are pulled downwardly from their Fig. 53 positions to their Fig. 51 positions. Cam locks 884 are turned from their Fig. 53 positions to their Fig. 51 positions. The front track sections 838c now move upwardly from their Fig. 51 positions to their Fig. 49 positions. Simultaneously, backward movement of carrier bar takes place from its position in Fig. 51 to its position in Fig. 49 and the type and type wedges 230 and 232 and the U-shaped wedges 440 are thereby carried along with said carrier bar.

Slides 806 move backwardly with the carrier bar 438 but they also move laterally away from each other from their Fig. 52 positions to their Fig. 50 positions and this lateral outward movement of said slides continues until their Fig. 48 positions are reached. Simultaneously, bellows 608 expands from its contracted condition as shown in Fig. 52 to its expanded condition as shown in Fig. 50 and the process of expansion continues until the fully expanded condition illustrated in Fig. 48 is attained. It will be recalled that the bellows is in engagement with the type and type wedges on the carrier bar through the instrumentality of downwardly extending fingers or tongues 628. As the bellows expands, these fingers or tongues spread the type and type wedges apart to substantially their original positions on the carrier bar 438 as shown, for example, in Fig. 47 and Fig. 48. Slidable strips 822, 824 and 826 assist in the uniform spreading or expansion of bellows 608. Compare the respective positions of said strips in Fig. 52 with their positions in Fig. 50 and finally with their positions in Fig. 48. In the final stage of movement of the bellows backwardly to its original position, tongues or fingers 628 engage a spacer comb 970 which is provided with relatively wide, tapered approaches 972 to narrow slits 974. See Fig. 70. The spacing of slits 974 corresponds to the spacing of the type rings.

It has previously been mentioned, in connection with Fig. 37, that each tongue or finger 628 is provided with a backwardly projecting portion 630. It will now be understood that it is this backwardly extending portion 630 which enters the tapered approaches 972 and cams its way along the tapered sides of said approaches in order to enter slits 974. See Figs. 44 and 45. It will be noted in Fig. 48, for example, that comb 970 is slidably supported at its respective ends on plates 976. These plates are themselves supported on posts 978 which are supported on table top 698. See Fig. 70. It is through

these posts 978 that shaft 382 extends. See Fig. 48 and Fig. 70. Screws 980 secure plates 976 to posts 978 and it will be noted that screws 982 secure blocks 984 to said plates 976. It will be noted in Fig. 48 that blocks 984 are under-cut to receive the ends of comb 970. These blocks 984 prevent axial movement of said comb laterally of the machine as a whole and they also prevent vertical movement of said comb in upward direction. Plates 976 prevent vertical movement of comb 970 in downward direction but the comb remains free to move longitudinally of the machine, that is, forwardly and backwardly thereof, being guided in such movement by the under-cut portion of the two blocks 984.

Locking plates 986 are pivotally mounted on comb 970 by means of screws 988. A torsion spring (not shown) is mounted on each screw 988 to urge the locking plates 986 into engagement with blocks 984. As viewed in Fig. 70, the locking plate 986 shown therein is urged to move in clockwise direction into engagement with block 984. More particularly, each locking plate is provided with a tongue 990 which is engageable with a notch 992 formed in each block 984. When the tongue 990 of each locking plate 986 is in engagement with notch 992 of the corresponding block 984, comb 970 is locked against any movement either forwardly or backwardly of the machine.

It will be observed in Fig. 70 that each locking plate is provided with two lugs 994 and 996 respectively on the opposite side of tongue 990. These lugs are engageable by a downwardly extending lug 998 formed on plate 1000. This plate is secured by means of screws 808 previously mentioned to plate 810 and the top of each slide 806. As the carrier bar 438 moves backwardly to return the type and type wedges to the type rings, portions 630 of tongues or fingers 628 engage comb 970 to properly space the type and type wedges in accordance with the spacing of the type rings. Simultaneously, lugs 998 of plates 1000 are brought into engagement with lugs 994 of the two locking plates 986. Further backward movement of the carrier bar causes said lugs 998 to pivot the locking plates 986 to disengage their tongues 990 from notches 992 of blocks 984. Comb 970 is now free to move backwardly with the carrier bar and such backward movement results from continued engagement of lugs 998 with lugs 994. See Figs. 48 and 70.

The tongues or fingers 628 are now brought into engagement with another comb 1002 which may be integral with or connected to the two end plates 976 above mentioned. See Figs. 48 and 70. It will be noted that comb 1002 is provided with a series of slits 1004 and alternating with said slits, a second series of slits 1006. Slits 1004 are longer than slits 1006 and they communicate with a hole 1008 which is formed in comb 1002 a spaced distance from the ends of said slits 1004. These holes 1008 render fingers 1010 formed between the two sets of slits relatively flexible and springy or resilient. Tapered approaches 1012 are formed at the front or open ends of slits 1004 and 1006 so as to facilitate entry of the tongues or fingers 628 of the bellows. Such entry is effected upon backward movement of carrier bar 438 and the resulting backward movement of comb 970. See Figs. 47, 48 and 70.

It will be noted in Figs. 47 and 48 that the upper tapered ends of U-shaped wedges 440 project into slits 1006 precisely as tongues 628 project into slits 1004. It will be understood that it is important for the U-shaped wedges to be accurately spaced so that they may readily be returned to their stored positions as viewed, for example, in Fig. 43. Slits 1006 in comb 1002 perform the same function with regard to the U-shaped wedges 440 that slits 974 in comb 970 perform with respect to laterally projecting portions 630 of tongues or fingers 628. Slits 1004 in comb 1002 are aligned with slits 974 in comb 970 to receive and accommodate said laterally pro-

jecting portions 630 upon rearward movement of the carrier bar 438 and bellows 608 and also comb 970 to their rearmost positions. It will be understood that when the carrier bar and the bellows again move forwardly on the next cycle, comb 970 will lag behind until lugs 998 engage lugs 996 of the two locking plates 986. These locking plates will move forwardly in engagement with lugs 998 until notches 992 are reached by lugs 990. The spring tension on locking plates 986 will cause them to turn on screws 988 so as to bring lugs 990 into engagement with notches 992. This will lock the locking plates against further movement forwardly of the machine and consequently comb 970 will be locked against further movement in said direction.

It has been stated that holes 1008 render fingers 1010 somewhat resilient. Another important function that these holes perform is to provide access to screw plugs 398 in order to adjust the tension of springs 390. See Figs. 32 and 33. Another important feature of fingers 1010 is the series of tapered undersides 1014 which enable the U-shaped wedges 440 to cam their way into slits 1006 on the upward movement of said U-shaped wedges from their stored positions. These tapered undersides perform the same function on the upward movement of said U-shaped wedges as tapered approaches 1012 perform on the rearward movement of said U-shaped wedges as above described.

The several operations of the machine above described follow a predetermined sequence which may best be understood in connection with Fig. 66 of the drawing. Fig. 66 is a schematic view indicating the timing of the machine and it relates particularly to the sequence of operations effected by the rotation of cam shaft 276. The radial lines marked 0, 10, 20, 30, 40 and so on up to 350 are intended to represent every tenth degree of angular movement of the cam shaft. In stage 1 which coincides with marginal line 0, the type wheels turn and stop at selected positions relating to the location of the type and type wedges in said type wheels or rings. The arcuate line marked 2 represents the stage in which the selected type and type wedges are pushed out of the type rings by the push-out comb 236 as shown, for example, in Fig. 43. See also Fig. 10.

The arcuate line in Fig. 66 marked 3 represents the third stage in the operations of the machine in which the type and type wedges are turned upright by the aligning cylinders 302 as shown, for example, in Figs. 44 and 45. Arcuate line 4 indicates that type aligners 372 are arrested, that is, maintained out of engagement with the selected pieces of type and type wedges. See Fig. 45. See also Figs. 16 and 9 as to stages 3 and 4 respectively.

Arcuate line 5 indicates the stage at which selected locking plates 544 are released by selector bars 470 for engagement with pusher bars 542. See Fig. 58 and Fig. 55. Arcuate line 6 corresponds to the stage at which the type aligners 372 are released for downward movement under the action of springs 390 into engagement with the selected type and type wedges to cam them into true vertical positions. See Figs. 46 and 9.

Arcuate line 7 in Fig. 66 represents the stage at which the type push-out comb is pulled back to inoperative position. See Figs. 10 and 28. In stage 8 as represented by the arcuate line marked 8 in Fig. 66, the U-shaped wedges 440 which were selected in stage 5 are elevated into engagement with carrier bar 438 and with the selected type wedges 232. See, for example, Figs. 61 and 11. In stage 9, represented by the arcuate line marked 9 in Fig. 66, which, it will be observed is coextensive with arcuate line 8, the type push-back comb 304, 306 is pulled downwardly from its Fig. 43 position where it serves as a stop for the type and type wedges which are pushed out of the type rings, to its Fig. 70 position where it is out of the way of the carrier bar 438 and the various elements which move with the carrier bar. See also Fig. 14.

Arcuate line 10 in Fig. 66 represents the stage at which

the type and type wedge holders or fingers 628 are moved into slots 634 and 632 of said type and type wedges. See, for example, Fig. 47. See also Fig. 8. Arcuate line 11 represents the stage at which the type aligners 372 are elevated out of engagement with the type and type wedges. The movement of said type aligners would be back from their Fig. 46 positions to their Fig. 45 positions. Arcuate line 12 coincides with arcuate line 11. Arcuate line 12 represents the stage at which locking plates 544 are returned to their inoperative positions, locking plate 544 on the right side of Fig. 58 being shown in operative position and the two locking plates 544 at the left of Fig. 58 being shown in their arrested or inoperative positions. See also Fig. 9 relative to stage 11 and Fig. 11 relative to stage 12.

Radial line 13 coinciding with radial line 130 (degrees) represents the stage at which the type carrier bar is moved forwardly across the table. See Fig. 70 and Fig. 2. Arcuate line 14 represents the stage during which the type and type wedges are closed. Slides 806 move laterally inwardly toward each other under the influence of cam tracks or slots 802 and the bellows is compressed and the type and type wedges are brought close together. Simultaneously, the U-shaped wedges 440 ride in tracks 840 and they too are brought into close proximity to each other and to the type wedges. See Fig. 70. Arcuate line 15 represents the stage at which the U-shaped wedge lifters are lowered with said U-shaped wedges and track sections 838c from their Fig. 49 positions to their Fig. 51 positions. See also Fig. 15 and Fig. 70.

Arcuate line 16 is co-extensive with arcuate line 15 and it represents the type clamping stage during the course of which the U-shaped wedges are elevated to their Fig. 53 positions into wedging engagement with type wedges 232 and type 230 and it is during this stage that cam locks 884 clamp down upon said type and type wedges 230 and 232 respectively. See also Fig. 15 in relation to the upward movement of the U-shaped wedges 440 and Fig. 12 in relation to the clamping action of cams 884.

Radial line 17 represents the type reproduction or printing stage. See Fig. 54. Arcuate line 18 follows radial line 17 by approximately the same angular distance that arcuate line 14 precedes said radial line 17 and it will be noted that radial line 17 is approximately 180 degrees or a half turn of cam shaft 276 beyond radial line 1 above mentioned. Arcuate line 18 represents the wedge opening stage following the type reproducing or printing operation. The U-shaped wedges 440 are brought downwardly from their Fig. 53 positions to their Fig. 51 positions. See also Fig. 15. Arcuate line 19 represents the clamp opening stage wherein cam locks 884 are turned from their Fig. 53 positions to their Fig. 51 positions. See also Fig. 12.

Radial line 20 shown in Fig. 66 coincides with the radial line midway between lines 230 (degrees) and 240 (degrees). Consequently, it will be understood that radial line 20 is 235 degrees removed from the starting line 1. Radial line 20 represents the stage in which the type carrier bar 438 and the type and type wedges 230 and 232 respectively, the U-shaped wedges 440 and the bellows are all moved backwardly across the table. See Figs. 70 and 2. Arcuate line 21 represents the stage at which the type and type wedge holders (tongues or fingers 628) are lifted out of engagement with the type and type wedges 230 and 232 respectively. In other words, they are lifted from their Fig. 47 positions to their Fig. 44 positions. See also Fig. 8.

Arcuate line 22 corresponds to the stage at which the U-shaped wedges 440 are returned from their Fig. 47 positions to their Fig. 43 positions. They simply drop down under their own weight when the carrier bar reaches its Fig. 43 position. But it is necessary, of course, that the pusher bars 542 be first returned to their Fig. 60 positions. See Fig. 13. Arcuate line 23 represents the stage at which the type push back comb 304, 306 is

moved upwardly to its Fig. 47 position. See also Fig. 14. Arcuate line 24 corresponds to the stage at which the type and type wedges 230 and 232 respectively are turned by the type aligning cylinders 302 from their vertical positions as shown in Fig. 44 to their horizontal positions, that is, on their sides, as shown in Fig. 43. See also Fig. 16. Arcuate line 25 indicates the step in which the type aligners 372 are released for downward movement under the action of springs 390. See Fig. 9. At this stage, however, there will be no engagement between said type aligners and the type and type wedges 230 and 232 respectively since the latter are flat on their sides.

Arcuate line 26 represents the stage in which the type push-back comb 304, 306 pushes the type and type wedges 230 and 232 respectively back into the type rings. See Fig. 9. Arcuate line 27 represents the stage following the return of the type and type wedges to the type rings, said stage representing the return movement of the type push-back comb to its Fig. 43 position. See also Fig. 9. This latter operation terminates one complete cycle and it extends into the beginning of the next succeeding cycle as Fig. 66 clearly shows. The interrupted arcuate lines 28 simply indicate the rotation of the main cam shaft 276.

The foregoing is illustrative of a preferred form of this invention and it will be understood that this preferred form may be modified and other forms may be provided within the broad spirit of the invention and the broad scope of the claims.

Mechanical cam operations

1. Type wheels turn and stop at the desired types.
2. Types pushed out.
- 35 3. Types turned upright.
4. Type aligners arrested.
5. Wedge selectors released.
6. Type aligners released.
7. Type push-out comb pulled back.
- 40 8. Wedges lifted into position.
9. Type push-back comb pulled down.
10. Type holders pushed into types.
11. Type aligners arrested.
12. Wedge selectors arrested.
- 45 13. Type carrier bar carried across table.
14. Wedges closed.
15. Wedge lifters lowered.
16. Types clamped.
17. Printing.
- 50 18. Wedges opened.
19. Type clamp opened.
20. Type carrier bar carried back.
21. Type holders pulled out of types.
22. Wedges stored.
- 55 23. Type push-back comb pushed up.
24. Types turned flat.
25. Type aligners released.
26. Types pushed back into wheel.
27. Type push-back comb pulled back.
- 60 28. Main cam shaft rotating.

Sequence of operations on type setting machines

As the prepared control tape 438c is inserted into the control unit, the stop contact 539c is closed by the tape pressing down the saw tooth fin 537c. Closing of contact 539c activates relay 641c—642c, which closes contact 640c and opens contact 643c. If the power switch 638c is closed, motor 510c moves tape by means of sprocket wheel 501c through the control unit.

As the line stop contact fin 537c gets into the approaching line stop hole 541c in the control tape, contact 539c opens, the relay 641c—642c is released, contact 640c opened and the tape transport motor 510c stopped. Contact 643c is closed at the same time and activates relay 75 633c over contact 484c which at that time is closed by

the fin 650c on cam 479c. Cam shaft 454c is turned 180 degrees as shown in Fig. 82.

Activating of relay 633c closes contact 632c—639c and motor 471c starts turning shaft 454c with cams and eccentric 455c.

First the contact 483c on cam 478c is closed and overtakes the duty of contact 484c on cam 479c. This is required to permit stopping of plate action motor 471c without energizing the relay 641c—642c and starting the tape transport motor 510c.

As the plate action proceeds, the contact plates 397c—396c and the tape are moved against the contact needles 394c—395c by the eccentric 455c.

Needles which meet a hole pass through the tape and make contact with their respective contact plates 396c and 397c. Needles which meet solid tape are only lifted on their springs and give no further action on that line.

The contact cam shaft 454c is now turned so far that the contact 482c on setting machine position checker cam 477c is opened. If the setting machine is in its starting position, the upper contact 628c on cam 376c is closed and the opening of contact 482c on cam 477c is closed, and cam shaft 454c proceeds to turn.

If, on the contrary, the setting machine is not in starting position and the contact 628c on cam 376c is open, the opening of contact 482c on cam 477c releases the relay 633c and stops the control unit until the setting machine gets in starting position and closes the contact 628c on position reporting cam 376c. This is designed, because it is not desired to apply selector voltage to the setting machine before it is in its starting position.

Now the cam shaft 454c proceeds and next the contacts 604c and 607c on cam 476c are closed. The upper contact 694c energizes the relay 564c which by closing contact 563c prepares the wheel stop solenoid 356c power circuits for completing.

The lower contact 607c on cam 476c energizes the relay 608c, which by closing contact 571c applies power to the contact plates 396c and 397c and through the contact needles, which are in contact with the plates, the corresponding case selector brushes 365c and type selector contacts 360c are energized.

Further turning of cam shaft 454c causes the opening of contact 483c on cam 478c, relay 633c releases; opens contact 639c and motor 471c stops. This is the position shown in Fig. 82.

The operations at the type setting machine now start. In its starting position, which is shown in Figs. 81 and 83, the lower contact 601c on cam 374c is closed. That means—relay 600c and contact 554c too are closed. Likewise closed are contacts 559c—560c at wheel stop solenoids 356c because the solenoids are open.

When the power switch 550c is closed, wheel drive motors 178 are under power and the type wheels are turning. When one of the case selector brushes 365c and one of the type selector contacts 360c becomes energized, as explained above, the following happens.

If the energized brush 365c happens to have at the moment of closing contact 571c, Fig. 82, already passed the slow-down contact 2, it will go through the tape selector contacts 360c and hit the energized one. In that case a circuit closes: Power lead 570c—contact 571c—contact plate 397c—contact needle 395c—selector contact 360c—selector brush 365c—needle 394c—contact plate 396c—resistor 1c—close contact 3c of relay 558c and power lead 589c.

The purpose of resistor 1c is to prevent a short circuit between power leads 570c and 589c, so nothing happens and the type wheel proceeds turning until the energized case selector brush 365c approaches and hits slow-down contact 2c. Now a circuit closes as follows: Power lead 570c—contact 571c—relay 558c—slow-down contact 2c—case selector brush 365c—contact needle 394c—contact plate 396c—resistor 1c—still closed contact 3c on relay 558c—power lead 589c. Relay 558c closes and its

contacts 557c connects resistor 561c in parallel to the rotor of motor 178 and resistor 561a in series to the stator of the same motor, thus slowing down the revolutions of the motor, but keeping its power. Contact 3c disconnects resistor 1c; contact 4c connects relay 558c direct to power lead 589c to hold relay 558c, when brush 365c leaves contact 2c, contact 5c connects one lead of relay 568c to power lead 589c (through contact 4c), to prepare relay 568c for operation.

Now brush 365c proceeds and meets energized type selector contact 360c. Circuit closes as follows: Power lead 570c—contact 571c, contact plate 397c—contact needle 395c selector contact 360c—brush 365c—contact needle 394c—contact plate 396c—relay 568c—contact 5c—contact 4c—power lead 589c.

Relay 568c operates and closes its contacts 567c and 6c, contact 6c connects relay 568 direct to power lead 570c (the entire circuit becomes power lead 570c—contact 571c—contact 6c—relay 568c—contact 5c—contact 4c—power lead 589c, to hold relay 568c, because brush 365c overshoots selector contact 360c to some extent at stopping the typewheel and may lose contact. Contact 567c closes the following circuit: line power lead 552c—contact 567c—contact 565c—566c at wheel stop solenoid 182—coil of solenoid—contact 563c on relay 564c—line power lead 551c.

Wheel stop solenoid 356c operates, throws its gear segment into gear of the type wheel and stops it. As the wheel stop solenoid closes, following contact changes happen: contact 565c leaves contact 566c and makes contact with 573c thus connecting coil of solenoid 182 direct to line power lead 552c to hold solenoid. Contacts 559c—560c are disconnected and stop wheel drive motor 178. Contact 596c (which in fact is one contact of the series of connected contacts 598c located one on every wheel stop solenoid) closes.

When all wheels are stopped in the described way, the last closing contact 598c completes the following circuit: Power line 589c—starter relay 592c of main cam shaft motor 284—contact 579c on cam 577c—Fig. 84—contact 372c on cam 370c of type carrier bar drive shaft 700, Fig. 83—all contacts 598c—power lead 570c.

Relay 592c operates, closes contact 591c and motor 284 starts turning main cam shaft 276. Only the electrical cams are shown but this shaft 276 also carries all mechanical operations cams. Now a number of electrical and mechanical operations start.

First the electrical:

Contact 601c on cam 374c opens, relay 600c opens contact 554c. This is done for the following reason: If for some reason line power would fail while wheels are stopped at different positions and types are out, wheel stop solenoids would drop open and close contacts 559c—560c. At return of power wheel drive motors would start turning and move the type wheels away, and it would be quite impossible to get the types back in their correct places. In this way wheel drive motor can operate only when the machine is in its starting position.

Contact 603c closes, connecting relay 564c direct to power lead 570c to prevent throwing out wheel stop solenoids when contact 684 on cam 476c, Fig. 82 will be opened when control unit is started for the next line.

Contact 628c on cam 376c is opened and remains open until the setting machine is again in its starting position. Contact 629c on the same cam is closed briefly. This shorts the opened contact 483c on cam 478c of the control unit and with this we leave for a while the setting machine and return to the control unit, as the shorting of contact 483c operates again relay 633c and starts motor 471c. Shaft 454c starts turning and the following happens: Eccentric 455c moves contact plates 396c and 397c away from contact needles 394c and 395c and frees tape 438c.

Contact 607c opens and releases relay 608c, which opens contact 571c disconnecting power from the contact

plate 397c and releases relays 558c and 568c at the setting machine.

Contact 607c also opens, but this has no effect, as it is shortened by the contact 603c on cam 374c at setting machine as was shown before. Cam 478c closes contact 843c in order to keep relay 633c closed as contact 629c on cam (Fig. 83) opens. After these contact changes are made, shaft 454c proceeds moving until eccentric 455c has completely freed tape 438c.

Now fin 645c on cam 475c has reached contact 480c and closing its shorts contact 539c causing relay 641c—642c to operate and start motor 510c. Tape 438c starts moving. Cam 475c proceeds and contact 480c is opened, but in the meantime tape 438c has pressed down contact fin 537c and closed contact 539c.

Notch 647c on cam 478c has reached contact 483c and opening it releases relay 633c and stops motor 471c, while motor 510c remains running. At the same time fin 650c on cam 479c has closed contact 484c and prepared circuit for starting motor 471c, when the next line stop hole 541c in tape 438c releases contact fin 537c, contact 539c and relay 641c—642c.

Push button switch 625c is provided for starting motor 471c manually, independent of the operation of the setting machine. The cycle for the control unit is now completed. Simultaneously with the already described electrical operations, the starting movement of shaft 102c causes mechanical operations as shown in diagram (Fig. 66). The start is shown at 0°. Operation 27 is completed; operations 2-12 are started and completed.

At 130° the upward step of cam 375c has reached contacts 624c and 625c. Contact 624c is opened, which has no effect at the present. Contact 625c is closed, which completes the following circuit: Power lead 579c—contact 625c on cam 375c—contact 618c on cam 371c located on the eccentric wheel shaft 700 which moves the type carrier bar across the table and back—relay 612c—power lead 589c. Relay 612c closes contact 611c and motor 714 starts turning shaft 700.

Cam 370c opens contact 372c, which interrupts the former described circuit, which started motor 284 and thus stops the same motor. Motor 714 moves the type carrier bar across the table. At that instant the shaft 700 has turned at 180°, cam 370c closes contact 372c and starts motor 284 again. Cam 371c opens contact 618c, which stops motor 714, and closes contact 619c which prepares circuit for next starting of motor 714 by cam 375c.

Motor 284 proceeds turning shaft 276 and the mechanical operations 14, 15 and 16 (Fig. 66) are completed. At that instant (182° in Fig. 66) fin 586c on cam 377c has reached contact 380c and closes it.

This operates relay 584c, Fig. 84, which closes contact 582c and starts motor 576c. This is the drive motor of any attachment designed for the setting machine to do either printing, matrix cutting or slug casting, which would have on its shaft, represented in Fig. 84 as 575c, the cams 577c and 578c.

As motor 576c starts turning shaft 575c cam 578c closes contact 580c which overtakes the duty of contact 380c, which is opened again as both motors (284 and 576c) run for a little while simultaneously.

Cam 577 opens contact 579c, which again interrupts the circuit for motor 284 and stops it. As shaft 575c has completed one revolution, cam 578c opens contact 580c and stops motor 576c, cam 577c closes contact and starts again motor 284.

Mechanical cams on camshaft 102c now complete their operations 18 and 19 (Fig. 66). At that instant the downward step on cam 375c has reached contacts 624c, 625c. Contact 625c is opened and contact 624c closes again.

Bearing in mind that on cam 371c contact 618c is open and contact 619c is closed at that time, motor 714 is started again and starts moving type carrier bar across

the table back to the type wheels. Contact 372c is opened by cam 370c and stops motor 284.

As shaft 700 has moved 180° again (type carrier bar is back at the wheels) cam 371c opens contact 619c which stops motor 714, closes contact 618c preparing next start of motor 714 and cam 370c closes contact 375c, thus starting once more motor 284.

Mechanical cams on shaft 276 now complete operations 21-26 and part of operation 27 (Fig. 66). At that time notch on cam 374c has reached contacts 601c—603c. Contact 603c opens and interrupts the circuit holding relay 564c. Contact 563c opens and all wheel stop solenoids 356c drop open. With this contacts 598c open and stop motor 284. Contact 601c on cam 374c is closed, relay 600c closes contact 554c and, as the wheel stop solenoids 356c have closed contacts 559c—560c, motors 178 start turning type wheels.

Cam 376c on shaft 276 has closed contact 628c, which reports to the control unit that the setting machine is in starting position. The entire cycle is now completed and the selecting of the next line starts.

What is claimed is:

1. A type setting machine, comprising a plurality of type and type wedge supporting rings which are rotatably mounted side by side on a common horizontal axis, radial slots formed in said rings for the type and type wedges, drive means individually connected to said rings for individual rotation thereof, locking means individually related to said rings for individually stopping said rings in selected angular positions, a carrier bar for said type and type wedges mounted in parallel relation to the horizontal axis of said rings and movable on a horizontal plane toward and away from said rings, reciprocating drive means connected to said carrier bar for moving said carrier bar rearwardly to a rear position adjacent said rings and forwardly to a forward position removed from said rings, a push-out comb mounted within the rings for forward and rearward radial movement on a horizontal plane, reciprocating drive means connected to said push-out comb to cause it to move forwardly into engagement with selected type and type wedges in said rings after the rings are stopped in selected angular positions to push said type and type wedges out of their respective slots in said rings and onto said carrier bar, holding means on said carrier bar for holding the type and type wedges thereon while permitting relative horizontal movement between said type and type wedges toward and away from each other longitudinally of said carrier bar, a plurality of wedges complementary to said type wedges stored adjacent said carrier bar when the carrier bar is in its rear position adjacent the rings, pushing means individually related to said complementary wedges for pushing selected complementary wedges into complementary positions adjacent the type wedges on said carrier bar and into engagement with said carrier bar for movement therewith, said complementary wedges being free to move relative to each other and relative to the type and type wedges longitudinally of the carrier bar, compressing means on said carrier bar for moving the type and type wedges together as the carrier bar is moved forwardly to forward position, guide means engaging said complementary wedges for guiding them toward each other and toward the type wedges in synchronization with the inwardly moving type and type wedges on said carrier bar as the carrier bar is moved forwardly to forward position, clamping means for clamping said type and type wedges upon said carrier bar when the carrier bar is in its forward position, and pushing means engageable with said complementary wedges for pushing them into wedged positions relative to said type wedges on said carrier bar, thereby wedging said type and type wedges on said carrier bar in justified, operative positions for type reproduction purposes.

2. A type setting machine in accordance with claim 1, wherein a type and type wedge stop comb is provided

outside the type and type wedge supporting rings in line with the push-out comb which is disposed within said rings and in line with the type and type wedges which are pushed out of said rings by said push-out comb, said stop comb being engageable by the type and type wedges which are pushed out of said rings to stop said type and type wedges in laterally aligned positions on said carrier bar.

3. A type setting machine in accordance with claim 1, wherein a type and type wedge stop comb is provided outside the type and type wedge supporting rings in line with the push-out comb which is disposed within said rings and in line with the type and type wedges which are pushed out of said rings by said push-out comb, said stop comb being engageable by the type and type wedges which are pushed out of said rings to stop said type and type wedges in laterally aligned positions on said carrier bar, said stop comb being mounted for vertical movement into and out of alignment with said push-out comb and said pushed out type and type wedges, and reciprocating drive means connected to said stop comb to move it into alignment with said push-out comb in order to serve as a stop for the type and type wedges which are pushed out of said rings, and to move it out of alignment with said push-out comb and pushed-out type and type wedges to clear the way for forward movement of said carrier bar and the type and type wedges which have been pushed onto said carrier bar, said stop comb remaining in its last mentioned position to clear the way for rearward movement of said carrier bar and the type and type wedges carried thereby back to the rear position of said carrier bar adjacent said rings.

4. A type setting machine in accordance with claim 1, wherein a type and type wedge stop comb is provided outside the type and type wedge supporting rings in line with the push-out comb which is disposed within said rings and in line with the type and type wedges which are pushed out of said rings by said push-out comb, said stop comb being engageable by the type and type wedges which are pushed out of said rings to stop said type and type wedges in laterally aligned positions on said carrier bar, said stop comb being mounted for vertical movement which are pushed onto said carrier bar to clear the way for forward movement of said carrier bar and said type and type wedges to the forward position of said carrier bar and for rearward movement of said carrier bar and said type and type wedges to the rear position of said carrier bar, reciprocating drive means connected to said stop comb for moving it vertically out of the way of the carrier bar and said type and type wedges prior to the movement of said carrier bar from its rear to its forward position, and for moving said stop comb vertically back to alignment with the push-out comb and said pushed-out type and type wedges after the carrier bar moves backwardly to its rear position, said stop comb serving also as a push-back comb and being mounted for horizontal movement when it is in alignment with said push-out comb and said pushed-out type and type wedges, and reciprocating drive means connected to said stop comb for moving said stop comb horizontally rearwardly to push the pushed out type and type wedges back into said rings following the return of said carrier bar to its rear position, and for moving said stop comb horizontally forwardly after the type and type wedges are returned to said rings to disengage said type and type wedges.

5. A type setting machine in accordance with claim 1, wherein a push-back comb is provided outside the rings and in alignment with the push-out comb and with the pushed-out type and type wedges on said carrier bar after the carrier bar is moved backwardly to its rear position adjacent said rings, said push-back comb being mounted for forward and rearward movement on the horizontal plane of movement of the push-out comb, and reciprocating drive means connected to said push-back

5 comb for moving said push-back comb horizontally rearwardly into engagement with said pushed-out type and type wedges to push them back into said rings and for moving said push-back comb horizontally forwardly out of engagement with said type and type wedges after they have been pushed back into said rings.

6. A type setting machine in accordance with claim 1, wherein the type and type wedge rings are mounted on external bearings which engage the outer peripheral edges of said rings to maintain them in axial alignment with each other.

10 15 20 15 25 30 35 40 45 50 55 60 65 70 75 75

7. A type setting machine in accordance with claim 1, wherein the type and type wedge rings are mounted on external rollers whose axes parallel the common axis of said rings, said rollers serving as bearings to support said rings in axial alignment with each other and to enable said rings to rotate on said common axis, each of said rings being provided with its own external rollers to facilitate individual rotary movement thereof independently of the other rings.

8. A type setting machine in accordance with claim 1, wherein the individual drive means which causes rotation of the individual type and type wedge rings comprises a plurality of gear teeth formed along the entire outer peripheral edge of each ring, a gear wheel in engagement with the gear teeth of each ring, and motorized drive means connected to each said gear wheel for rotating the same and thereby causing rotation of the ring whose gear teeth said gear wheel engages.

25 30 35 40 45 50 55 60 65 70 75 75

9. A type setting machine in accordance with claim 1, wherein the locking means for individually stopping the type and type wedge rings in selected angular positions comprises as to each ring, a plurality of gear teeth formed along the entire peripheral edge of said ring, a toothed locking member mounted for reciprocating movement into and out of engagement with said gear teeth, and a solenoid linked to said locking member to move said locking member into locking engagement with said gear teeth when the solenoid is energized, a spring being connected to said locking member for moving it out of locking engagement with said gear teeth when the solenoid is de-energized.

10. A type setting machine in accordance with claim 1, wherein each ring is provided with a plurality of gear teeth formed along its entire peripheral edge, the drive means which individually drives each said ring comprising a motor-driven gear wheel which engages said gear teeth and which causes each ring to rotate when the motor is energized, the locking means which individually stops each said ring comprising a solenoid actuated toothed locking member which is mounted for movement into and out of engagement with the gear teeth of each said ring, said locking member being brought into locking engagement with the gear teeth of each individual ring when the solenoid is energized and the motor is de-energized, a spring being connected to each said locking member to disengage it from the gear teeth of the ring to which it is individual when the solenoid which actuates it is de-energized, thereby freeing the ring for rotary movement when the motor which drives the ring is again energized.

11. A type setting machine in accordance with claim 1, wherein the type and type wedges are stored flat on their sides in the radial slots which are formed in the type and type wedge rings, type and type wedge turning cylinders being provided outside said rings in alignment with the push-out comb and the type and type wedges which are selected to be pushed out of said rings, said cylinders being mounted for angular movement about their respective axes and being positioned to receive the type and type wedges which are pushed out of said rings onto said carrier bar, reciprocating actuating means being connected to said cylinders to turn them in one direction an angular distance of 90 degrees in order to turn said pushed-out type and type wedges to vertical positions on said carrier

bar prior to being engaged and held thereon by said holding means and prior to the forward movement of said carrier bar from its rear to its forward position, said cylinders being positioned to receive said pushed-out type and type wedges after the return of said carrier bar to its rear position from its forward position, said reciprocating actuating means thereupon causing said cylinders to turn in the opposite direction an angular distance of 90 degrees in order to turn said pushed-out type and type wedges back to their original positions flat on their sides so that they may be returned to their respective slots in said rings.

12. A type setting machine in accordance with claim 1, wherein the type and type wedges are stored flat on their sides in the radial slots formed in said type and type wedge rings, angularly movable means being provided for engagement with each of the type and type wedges which are pushed out of said rings, said angularly movable means being adapted to turn said type and type wedges to vertical positions on said carrier bar prior to engagement of said type and type wedges by said holding means, said angularly movable means being also engageable with said type and type wedges after the carrier bar returns to its rear position from its forward position in order to turn said type and type wedges back upon their sides so that they may be returned to their respective slots in said rings.

13. A type setting machine in accordance with claim 1, wherein the type and type wedges are stored flat on their sides in the radial slots formed in said type and type wedge rings, angularly movable means being provided to receive each of the type and type wedges which are pushed out of said rings onto said carrier bar, said angularly movable means being adapted first to turn said type and type wedges to substantially vertical positions on said carrier bar and subsequently to turn said type and type wedges back upon their sides, aligning means for individually aligning said type and type wedges so that they will assume perfect vertical positions, said aligning means being vertically movable into engagement with said type and type wedges to vertically align them on said carrier bar and being vertically movable out of engagement with said type and type wedges to free them for turning movement back upon their sides so that they may be returned to their respective slots in said rings.

14. A type setting machine in accordance with claim 1, wherein the type and type wedges which are pushed out of the type and type wedge rings are flat on their sides in said rings prior to being pushed out of said rings and remain flat on their sides during the push-out operation, angularly movable means being provided for engagement of said type and type wedges after they are pushed onto the carrier bar to turn them to approximately vertical positions, vertical aligning means being provided for engagement with each of said type and type wedges to position them in perfectly vertical positions, each said vertical aligning means comprising a vertically movable cam member which is movable in one direction into engagement with the type or type wedge to which it is related and which is movable in the opposite direction out of engagement therewith, each said cam member being provided with two converging cam faces which engage the type or type wedge between them.

15. A type setting machine in accordance with claim 1, wherein the carrier bar is provided with a key bar extending substantially its full length, the type and type wedges being provided with notches formed therein to accommodate and engage said key bar in order to accurately position said type and type wedges on said carrier bar, said key bar being adapted to prevent relative movement between the type and type wedges which are in engagement therewith and the carrier bar transversely of said carrier bar, said type and type wedges being free to move relative to each other, toward and away from each other, and relative to the carrier bar longitudinally thereof.

16. A type setting machine in accordance with claim 1, wherein the type and type wedges which are pushed onto the carrier bar are keyed to said carrier bar to prevent relative movement between them and the carrier bar transversely of said carrier bar, said type and type wedges being free to move relative to each other toward and away from each other and relative to said carrier bar longitudinally thereof.

17. A type setting machine in accordance with claim 1, wherein the type and type wedges which are pushed onto the carrier bar are keyed to said carrier bar by means of a key bar on said carrier bar and notches formed in said type and type wedges to engage said key bar and thereby to prevent relative movement between said type and type wedges and the carrier bar transversely of said carrier bar on a horizontal plane, a retaining bar being mounted on said carrier bar on the opposite side of said type and type wedges from said carrier bar in order to prevent vertical movement of said type and type wedges relative to said carrier bar, said type and type wedges being free to move relative to each other toward and away from each other and relative to said carrier bar, key bar and retaining bar longitudinally thereof.

18. A type setting machine in accordance with claim 1, wherein the type and type wedges are provided with vertically extending slots, the holding means for holding said type and type wedges including a horizontally extending bellows which is mounted above the carrier bar in vertical alignment therewith and a plurality of holding fingers projecting vertically downwardly from said bellows into engagement with the slots in said type and type wedges.

19. A type setting machine in accordance with claim 1, wherein the type and type wedges are provided with vertically extending slots, the holding means for holding said type and type wedges including a horizontally extending bellows which is mounted above the carrier bar in vertical alignment therewith and a plurality of holding fingers projecting vertically downwardly from said bellows into engagement with the slots in said type and type wedges, the compressing means for moving the type and type wedges together including a pair of slides mounted on said carrier bar with the type and type wedges between them, said slides being in engagement with the ends of the bellows to support said bellows above the carrier bar, said slides being movable toward each other to compress the bellows and thereby to move the holding fingers and the type and type wedges which they engage toward each other, said slides being also movable away from each other to expand the bellows and thereby to spread and space the holding fingers and the type and type wedges which they engage.

20. A type setting machine in accordance with claim 1, wherein the compressing means for moving the type and type wedges together on the carrier bar as the carrier bar is moved forwardly to forward position comprises a pair of slides mounted on said carrier bar with the type and type wedges situated between them, said slides being slidably movable on said carrier bar toward each other, and being also slidably movable on said carrier bar away from each other, a bellows supported at its two ends by said slides, a plurality of downwardly extending type and type wedge holding fingers secured at their upper ends to said bellows and engaging with their lower ends said type and type wedges, whereby movement of said slides toward each other compresses the bellows and causes the holding fingers and the type and type wedges which they engage to move toward each other, and whereby movement of said slides away from each other causes the bellows to expand and to move the holding fingers and the type and type wedges which they engage to move apart from each other, cam tracks being provided on a horizontal plane parallel to and adjacent the horizontal plane of movement of the carrier bar, said cam tracks converging in the direction of the forward position of the carrier bar and diverging in the direction of the rear

position of the carrier bar, and cam followers on said slides which engage said cam tracks, whereby forward movement of the carrier bar causes the cam followers to move along the cam tracks in the converging paths of said cam tracks and thereby to move the slides toward each other and consequently to contract the bellows and to move the holding fingers and the type and type wedges which they engage toward each other, said compressing means being also the means of spreading the type and type wedges apart on the backward movement of the carrier bar, whereby the cam tracks cause the cam followers to travel in the diverging paths of said cam tracks and thereby to move the slides away from each other, thereby causing the bellows to expand and the holding fingers to move apart together with the type and type wedges which they engage.

21. A type setting machine in accordance with claim 1, wherein the complementary wedges are provided with tapered side faces and the type wedges are provided with tapered side portions, said tapered side faces and said tapered side portions being complementary to each other.

22. A type setting machine in accordance with claim 1, wherein each type wedge is provided on one side thereof with a tapered surface and wherein each complementary wedge is provided on one side thereof with a tapered face, said tapered surface and said tapered face being on facing sides for engagement with each other and being complementary to each other, whereby movement of the complementary wedges in one direction relative to the type wedges while the tapered faces of the complementary wedges are in engagement with the tapered surfaces of the type wedges causes a lateral movement of said type wedges and said complementary wedges away from each other, and movement of said complementary wedges in the opposite direction relative to said type wedges while the tapered faces of the complementary wedges are in engagement with the tapered surfaces of the type wedges causes a lateral movement of said type wedges and said complementary wedges toward each other.

23. A type setting machine in accordance with claim 1, wherein each complementary wedge comprises a U-shaped member which is movable into engagement with the carrier bar with its two arms engaging said carrier bar between them, one of said arms extending vertically in front of said carrier bar and the other arm extending vertically in back of said carrier bar, whereby said carrier bar and the complementary wedges which engage it are movable integrally with each other both forwardly and backwardly, said complementary wedges remaining free to move relative to each other toward and away from each other and relative to said carrier bar longitudinally thereof.

24. A type setting machine in accordance with claim 1, wherein each complementary wedge comprises a U-shaped member which is movable vertically upwardly into engagement with the carrier bar with its two arms engaging said carrier bar between them and which is movable vertically downwardly out of engagement with said carrier bar.

25. A type setting machine in accordance with claim 1, wherein each complementary wedge comprises a U-shaped member which is movable vertically upwardly into engagement with the carrier bar with its two arms engaging said carrier bar between them and which is movable vertically downwardly out of engagement with said carrier bar, one of the arms of each said complementary wedge being in abutment with the front of the carrier bar and the other arm being in abutment with the back of the carrier bar when the complementary wedge is in engagement therewith, whereby the complementary wedges which are in engagement with the carrier bar are movable integrally with said carrier bar in forward and backward direction, said complementary wedges being free for movement toward and away from each other longitudinally of said carrier bar.

26. A type setting machine in accordance with claim 1, wherein each complementary wedge comprises a U-shaped member with a tapered face on each of its two arms, both tapered faces occupying a common plane, and wherein in each type wedge is provided on one side with two spaced tapered surfaces which are engageable by the tapered faces of one of the complementary wedges when both the type wedge and the complementary wedge are in engagement with the carrier bar in side by side relationship, the tapered faces of the complementary wedge being complementary to the tapered surfaces of the type wedge.

27. A type setting machine in accordance with claim 1, wherein the complementary wedges are U-shaped members which are engageable with the carrier bar with their two arms engaging said carrier bar between them, thereby locking said complementary wedges to said carrier bar for integral forward and backward movement with said carrier bar, said complementary wedges being free to move relative to each other in lateral direction toward and away from each other longitudinally of said carrier bar, a plurality of horizontally extending guide tracks provided adjacent said carrier bar, said guide tracks converging in forward direction and diverging in rearward direction, said complementary wedges being provided with projecting members which slidably engage said guide tracks, whereby the complementary wedges are caused to move toward each other along the carrier bar when the carrier bar moves forwardly, by reason of the engagement of the projecting members of said complementary wedges with said converging guide tracks, and whereby the complementary wedges are caused to move away from each other along the carrier bar when the carrier bar moves backwardly, by reason of the engagement of the projecting members of said complementary wedges with said diverging guide tracks.

28. A type setting machine in accordance with claim 1, wherein the guide means which engage the complementary wedges for guiding them toward each other in synchronization with the movement of the type and type wedges toward each other as the carrier bar is moved forwardly comprises a plurality of guide tracks which occupy a horizontal plane adjacent the horizontal plane of movement of the carrier bar, said guide tracks converging in forward direction and diverging in rearward direction, said complementary wedges being provided with projecting members which engage said guide tracks and move in converging paths along said guide tracks on the forward movement of the carrier bar, thereby causing the complementary wedges to move toward each other and toward the type and type wedges along said carrier bar when said carrier bar moves forwardly, said projecting members being caused to move in diverging paths by said guide tracks on the rearward movement of said carrier bar, thereby causing the complementary wedges to move away from each other and from the type and type wedges along said carrier bar when the carrier bar moves rearwardly.

29. A type setting machine in accordance with claim 1, wherein the guide means which engages the complementary wedges for guiding them toward each other along the carrier bar when the carrier bar moves forwardly comprises a plurality of guide tracks, said complementary wedges being provided with means for engaging said guide tracks and for being guided thereby, said guide tracks being arranged in converging paths in forward direction and in diverging paths in rearward direction, said guide tracks serving also to move the complementary wedges away from each other along the carrier bar when the carrier bar moves rearwardly.

30. A type setting machine in accordance with claim 1, wherein the complementary wedges are stored below the carrier bar when the carrier bar is in its rear position, said complementary wedges being individually movable vertically upwardly into engagement with said carrier bar and being individually movable vertically downwardly from said carrier bar to disengage said carrier bar, said

complementary wedges being movable upwardly into engagement with the carrier bar by the pushing means which are individually related to said complementary wedges, said complementary wedges being movable downwardly out of engagement with said carrier bar by simply dropping under their own weight into their stored positions.

31. A type setting machine in accordance with claim 1, wherein the pushing means which is individually related to the complementary wedges for pushing selected complementary wedges into complementary positions adjacent the type wedges on said carrier bar and into engagement with said carrier bar for movement therewith, comprises a plurality of pusher bars which are individually aligned with said complementary wedges when said complementary wedges are in their stored positions, means for individually pushing said pusher bars into engagement with said complementary wedges to push said complementary wedges into engagement with said carrier bar, said means being normally out of engagement with said pusher bars and being individually movable into and out of engagement with said pusher bars, a plurality of selector bars mounted adjacent said pusher bars and said means for pushing the pusher bars into engagement with the complementary wedges, said selector bars being individually and selectively movable into engagement with the type and type wedges on the carrier bar, notches in said type wedges into which said selector bars are adapted to enter to assume a different position from the position which is assumed by the selector bars which engage the type on said carrier bar, said means for pushing the pusher bars being normally in engagement with said selector bars to prevent movement of said means into pushing engagement with said pusher bars, and notches formed in said selector bars for registration with said means for pushing the pusher bars when said selector bars are in engagement with the notches in the type wedges in order to disengage said means and to free said means for movement into pushing engagement with the pusher bars to which said released means are individually related.

32. A type setting machine in accordance with claim 1, wherein the guide means which engages the complementary wedges and guides them toward each other along the carrier bar as the carrier bar moves forwardly, comprises a plurality of guide tracks which are normally situated on a horizontal plane adjacent and parallel to the horizontal plane of movement of the carrier bar, said guide tracks being arranged in converging relation to each other in forward direction and in diverging relation to each other in rearward direction, said complementary wedges being provided with track engaging portions which slidably engage said guide tracks so as to guide said complementary wedges along converging paths as the carrier bar moves forwardly and so as to guide said complementary wedges in diverging paths as the carrier bar moves rearwardly, said tracks being divided into rear, intermediate and forward track sections, said intermediate track sections being permanently situated on said horizontal plane which is adjacent the plane of movement of the carrier bar and said intermediate track sections being always situated in fixed relation to each other, said rear track sections being fixed in relation to each other but being vertically movable into and out of said horizontal plane on which the intermediate track sections are permanently situated, said forward track sections being horizontally movable within a limited range relative to each other and being vertically movable into and out of said horizontal plane on which the intermediate track sections are permanently situated.

33. A type setting machine in accordance with claim 1, wherein a stop comb is provided outside the type and type wedge rings to engage and stop the type and type wedges which are pushed out of said rings in order to properly position said type and type wedges relative to

the carrier bar, said stop comb being vertically movable into and out of alignment with said type and type wedges, said stop comb being movable into alignment therewith in order to engage and stop said type and type wedges and being movable out of alignment therewith after the type and type wedges are stopped in proper position relative to the carrier bar in order to clear said type and type wedges and also the carrier bar for forward movement, the guide means which engages the complementary wedges and guides them toward each other along the carrier bar as the carrier bar moves forwardly comprising a plurality of guide tracks which are normally situated on a horizontal plane adjacent and parallel to the horizontal plane of movement of the carrier bar, said guide tracks being arranged in converging relation to each other in forward direction and in diverging relation to each other in rearward direction, said complementary wedges being provided with track engaging portions which slidably engage said guide tracks so as to guide said complementary wedges along converging paths as the carrier bar moves forwardly and along diverging paths as the carrier bar moves rearwardly, said tracks being divided into rear, intermediate and forward track sections, said intermediate track sections being permanently situated on said horizontal plane which is adjacent the plane of movement of the carrier bar, said rear track sections being mounted on said stop comb for vertical movement therewith, said stop comb being vertically movable between two positions wherein the stop comb is aligned for engagement with the type and type wedges and the rear track sections are out of alignment with said horizontal plane when the stop comb is in one of said positions, and wherein the stop comb is out of alignment with said type and type wedges and the rear track sections are in alignment with said horizontal plane when the stop comb is in the other of said positions.

34. A type setting machine in accordance with claim 1, wherein the guide means engaging the complementary wedges for guiding them toward each other along the carrier bar on the forward movement of said carrier bar comprises a plurality of guide tracks which are normally mounted on a horizontal plane adjacent and parallel to the plane of movement of the carrier bar, said guide tracks being arranged in converging relationship in forward direction and in diverging relationship in rearward direction, said complementary wedges being provided with track engaging members which slidably engage said guide tracks so as to guide the complementary wedges in converging paths on the forward movement of the carrier bar and also to guide said complementary wedges in diverging paths on the rearward movement of said carrier bar, said guide tracks including forward guide track sections which are vertically movable into and out of said horizontal plane, reciprocating means connected to said forward guide track sections causing them to move vertically relative to said horizontal plane, a horizontal bar mounted above said forward track sections and vertically movable therewith, notches formed in said complementary wedges for engagement with said bar, whereby vertical movement of said forward track sections in one direction out of said horizontal plane causes a corresponding vertical movement of said horizontal bar and said complementary wedges to move said complementary wedges into non-wedging engagement with the type wedges when said type wedges and the type are moved together on the carrier bar on the approach of said carrier bar to its forward position, the pushing means for pushing the complementary wedges into wedged positions relative to the type wedges on the carrier bar being now engageable with said complementary wedges to push them into wedging engagement with said type wedges to wedge the type wedges and type in justified operative positions on said carrier bar.

35. A type setting machine in accordance with claim 1,

wherein the type and type wedges and the complementary wedges are integrally movable with the carrier bar in its forward movement in the direction of its forward position, means engageable with the complementary wedges to move them downwardly relative to the carrier bar and the type and type wedges thereon as the carrier bar approaches its forward position and as the type and type wedges and the complementary wedges are moved toward each other longitudinally of the carrier bar, said pushing means which is engageable with the complementary wedges for pushing them into wedged positions relative to the type wedges on said carrier bar being actuated when the type, type wedges and complementary wedges are moved together on said carrier bar as far as they will go in order to push said complementary wedges upwardly into wedging engagement with said type wedges to wedge said type wedges and the type in justified operative positions on said carrier bar.

36. In a type setting machine, a table, a type and type wedge carrier bar mounted for movement across said table, a plurality of type and type wedges mounted on said carrier bar for movement therewith, means connected to said type and type wedges for moving them together on said carrier bar as the carrier bar moves across the table, wedges complementary to said type wedges engaging said carrier bar and movable therewith, a plurality of converging guide tracks formed in said table, said complementary wedges being in engagement with said converging guide tracks and being guided toward each other and toward the type and type wedges as the carrier bar moves across the table.

37. In a type setting machine in accordance with claim 36, said type wedges and said complementary wedges having complementary cam faces, said complementary wedges being movable relative to the type wedges and relative to the plane of movement of the carrier bar in order to exert a camming action against said type wedges to bring said type wedges into wedging engagement with the type.
38. In a type setting machine having a plurality of type and type wedges mounted side by side, a plurality of complementary wedges which are mounted for movable engagement with said type wedges, said type wedges and said complementary wedges being provided with complementary cam faces which exert a wedging action between said type wedges and said complementary wedges when said complementary wedges are moved in one direction relative to said type wedges, thereby exerting wedging pressure upon the type to lock said type in operative positions, said complementary wedges being U-shaped members whose two arms are both provided on one side with said cam faces and wherein the type wedges are also provided on one side with said cam faces, there being two such cam faces on each type wedge spaced in accordance with the spacing of the arms of the complementary wedges.
